PRINTING DEVICE

John William Armbruster, East Rockaway, N. Y., assignor, by mesne assignments, to International Business Machines Corporation, New York, N. Y., a corporation of New York

Original application February 5, 1930, Serial No. 425,966. Divided and this application August 12, 1931, Serial No. 556,584

19 Claims. (Cl. 101—93)

The primary object of this invention is to provide an improved form of printing mechanism. The printing mechanism in this case is shown to be under control of record cards perforated in code. However, it is apparent that the novel printing features disclosed may be applied to various other types of printing machines.

The primary object of this invention is to provide an improved form of printing mechanism. The printing mechanism in this case is shown to be under control of record cards perforated in code. However, it is apparent that the novel printing features disclosed may be applied to various other types of printing machines.

Another object of the invention is to provide devices for printing duplicate records in an improved way.

A feature of the invention is the printing of a plurality of lines of data on a record sheet in one operation. The printing mechanism includes interspersed type members for printing more than one line of data from one group of type members in a single operation.

Another feature of the invention is the printing of bills, receipts, etc. in the regular mailing form as an incident to the performance of other accounting operations.

Another object of the invention is to provide means for controlling printing according to the magnitude of the data presented for printing. The data presented is compared with predetermined names, numbers, and/or dates set up in the machine by the operator.

Another object of the invention is to control printing of totals according to the comparison of the data presented for printing with other predetermined data decided upon by the operator of the machine.

It is also an object of the present invention to provide printing devices which are adapted to print more data simultaneously than was before possible in machines of the tabulating or accounting class. The mechanism disclosed is adapted to print from one record card in one operation the same amount of data that before required three record cards and three operations of a machine.

By means of the present printing device a name, address, amount, etc. can now be printed in one operation and in the proper position on the record media. A feature of the printing devices is that an address may be printed directly under a name, in the standard mailing form, during a single operation of the machine. The position of the name and address on the record paper (it may be a bill, receipt, statement, etc.) is important, especially when used in the mails with a window envelope. To secure the novel results described above, related type bars are arranged alternately

between other type bars, and they are impressed against a platen by eccentrics. The use of these operating eccentrics results in a simple positive noiseless type of printing that does not require printing hammers and the space usually required for such devices. An additional feature of the printing devices is that they are constructed to print a duplicate record of all matter printed.

A more complete control of the functioning of an accounting machine is also an object of this invention. Heretofore, when a control of the functioning of a machine, such as no-print, was set, that control would prevail and would not be varied no matter what data was printed, added or totalled. The present machine provides control for many of the functions of the machine that is so devised that when the data presented by the record card does not satisfy predetermined requirements, which are decided upon and set up on the machine before its operation, the said controls will separate such data from the other data that does satisfy the requirements. Because of its complexity, this object will have to be explained in detail.

In this specification, it is assumed that the date scale starts at January and progresses along to December so that July would be higher than June in the chronological scale. In the alphabetic scale, *a* may be taken as the first letter and all other letters in order up to *z* may be mentioned hereinafter as being higher in the alphabetic scale.

An object is to make the control devices so that not only can one denomination of a number, or period of a date, or letter of a name, be the determining factor for control of printing, but, that a full number, date or name, may be the determining factor. The highest order of the number, etc. set up will not be the only order capable of manifesting that the data presented by the card is of a lower or higher place on the scale used, but every order of the setup has this power. If, for instance, 76.82 be set up for a control and 76.92 be presented by the record card, then the dimes order control devices will have the ability of manifesting that the number tendered is larger; if 77.62 be presented then the dollars order control will have this power of discrimination. The same is true of the controls in the date and alphabetic scales. When handling a number, a plurality of denominations in the control device are coupled so that control will not be exercised by a dimes, dollars or cents bank alone, although it is possible, but a full number consisting of the units, tens, hundreds, etc. denominations may

be set up on the controls and then said control will be affected by the full number of units, tens, etc. denominations presented by the punched card. In a like manner, when a date is considered, not alone can a certain year, month or day be made the controlling factor, but the full date of all three periods combined may control at the same time.

Control data comprising a date consisting of a certain year, month and day may be set up to simultaneously act as a unit in controlling according to the place in the date scale of a date on the punched card of a certain year, month, and day, which also acts as a unit. During name control in the present machine, the first letter or any letter of a name is not alone the sole determining factor of control, although it may be so used. In a novel fashion all the letters or a few of the letters of a name may at the same time be controlling factors in selective control, according to the place a name of a man, city, state, etc. presented on a punched card, occupies in the alphabetic scale. For example, the letters OMTIN may be decided upon as the control wished exercised over certain names about to be presented in the machine by punched cards. As the cards run through the machine and the control mechanism functions not only will names such as Prota or Winte, which are higher in the alphabetic scale than the first letter, influence the controls to make manifest that these names are higher in the alphabetic scale, but names such as Omtip or Omwal will have the same influence, even though the change in the alphabetic magnitude occurs in the center or at the end of a name. To exercise this novel control the devices are arranged so that the setting of manipulative elements to a certain place in the numerical, date, or alphabetic scales, plus the setting of an element to indicate whether control is desired above, below, or exactly at that certain place in the scale used, will, upon operation of the machine control devices, vary the regular printing of the data within the control of the two elements, from that data outside of the control of the range predetermined by the two elements.

The above mentioned manipulative elements are so situated and constructed that when they are set in a particular position above the related type bar or actuator, the movement of the actuator to an extent corresponding to the particular position held by the manipulative element presents a notch in the actuator and allows a controlling movement of the manipulative element to take place. On each side of the notch the actuator is cut to present a different level to the said element, thus affording an indication whether the actuator has moved more or less than the number set up.

The requirements which the operator of the machine may desire are made ready to exercise control by first setting up a certain amount, number, agent, age, policy number, date, operator, occupation, name or address, by the manipulative knobs provided for the purpose; then next he can require, by moving a lever, that the above data will control in one of five different ways. The first position "PRINT" of the lever denotes that the machine is to function in its usual fashion, which means it will print any data presented by the punched cards. The second position of the lever is the "above index" position. With the lever in this position, the machine will print only the data which includes a name, num-

ber or date which is higher in the numerical, dating or alphabetic scales than that set up by the manipulative knobs. Thus, if \$15.00 is set up by the knobs and a punched card presents data including the amount, \$15.00, or less, that data will not be printed. However, if the data included an amount of \$15.01 or more, the data would be printed.

In a like manner, if Dec 29, 21 is set up by the knobs and data is presented dated Dec 29, 21 or before, that date will not be printed, but if the data is dated Dec 30, 21 or later, printing will take place in the usual manner; so also if EN is set up by the name knobs and data is presented including a name such as ENRIGHT or EMSILL or a name lower in the alphabetic scale, that data will not be printed, however, if the data includes a name such as EODISE or EPSTEIN or a name higher in the alphabetic scale, then the data will be printed. Other data such as policy number, kind of occupation, address, etc. may be used to control in a similar fashion. By progressive set-ups of the name knobs, an alphabetical listing and sorting of a group of cards is possible. The third position of the lever is the "exact" position. With the lever in this position the machine will print only the data which includes a name, number, or date that is exactly the same as that requirement which is set up on the manipulative knobs by the operator of the machine. The fourth position of the lever is the "below index" position. Under this control the machine will print only the data including a name, number, or date which is smaller or lower in its scale than that set up on the adjustably set knobs. With this control, the action of the lever in the "above index" position is reversed. Taking the same examples of the setting of the manipulative knobs given above, then given data presenting \$14.99 or less, a date of Dec 28, 21 or earlier, a name of lower than Emsill in the alphabetic scale, such data will be printed, and any data higher in the respective scale will be rejected. The fifth position of the lever is the "no print" position. In this position a control is effected so that printing will not occur no matter what the data on the card or the setup of the adjustable knobs.

The above general discussion gives an outline of the control exercised by the manipulative control lever and adjustable knobs during the normal operation of the machine. Aside from the above, however, other special controls are provided for use during totalling operations to vary the control in accordance with conditions existing at such times. These novel features will next be described as additional objects of this invention.

The machine includes many novel methods of totalizer engaging during total taking. An accumulator control key is part of this mechanism. During regular adding operations this key determines whether adding will always take place or whether the adding will take place under control of the control section described above. When under such control, data not printed will also not be added. During totalling, however, depression of this key will result in novel control of the totalizer meshing with the actuator. The usual total, sub-total, and non-add keys are provided and they will normally cause the machine to time totalizer engagement with actuators in the usual fashion as is their action in most accounting machines. Under such normal conditions, the total key will, when depressed, cause clearing of the totalizer and printing of the amount standing thereon. The sub-total key will cause printing of

165

the amount standing on a totalizer, at the same time retaining the amount in the totalizer. The non-add key will, as its name implies, prevent adding. Now, however, depression of the accumulator control key in addition to one of the above mentioned keys will cause functioning not heretofore possible in any accounting machine and of decided utility in many uses of such machines. Depression of both the total and control keys will 10 result in a control of totalling by the amount standing on the totalizer.

The control level will be put in one of the five positions and the adjustable knobs mentioned above will be set to a particular amount. Then, 15 upon operation of the machine any amount not meeting the requirements set by the controls will change the totalizer meshing so that the amount taken out by the restoring of the totalizer to zero will again be put in the totalizer, thus changing 20 the totalling function to sub-totalling without printing. Therefore, the amount that does not satisfy requirements, or that for some other reason is wished retained, will be kept in the totalizer for all future operations such as additional adding operations, reference to in checking up delinquents in payment, or accounts overdrawn, etc. It is clear that the retaining of certain data 25 in the totalizers at times, even though they are set for zeroizing, is a useful method of operating the machine. With this type of use of the machine, it could be arranged so that printing on the detail strip will always occur. This may be done by an alternative method of construction as suggested above in connection with printing.

35 If the sub-total and accumulator control keys are both depressed there will result a control of changing this function by the amount standing on the totalizer. The controls being set and the machine being operated, then movement of the 40 actuators to an amount satisfying the requirements set by the controls, will change the totalizer meshing so that the amount rolled out of the totalizer wheels as they are brought to zero will not be rolled back in again, thus the sub- 45 totalling function will be changed to totalling. In this way any amount that satisfies set requirements, or for some other reason such as closing an account that is paid up, or clearing after a last installment is paid, is cleared out of the 50 totalizer.

The usefulness of clearing out a totalizer, when set for a sub-total is believed apparent. The ability of the machine to choose either a total or sub-total function and no print the data, depending upon the amount in the totalizer is believed 55 a very useful function. It is also contemplated that additional wheels could be put on the totalizer so that all the data now presented by the punched card could be held in a storage 60 totalizer and represented by positioned wheels. With this done, the totaling function could be varied and controlled not only by the amount standing on a totalizer but also by the date, name 65 or some other designation presented by the totalizer when a total is being taken therefrom.

Another method of control has been devised and is thought admirably fitted for use in the present machine. It departs only slightly from the construction of the controls mentioned above, 70 but effects an altogether different mode of control. The controls described in outline above, control when data is below, above or exactly at a certain point in alphabetic, dating or numerical scales. This other control would be exercised between 75 two points in a scale. One example is

control between two dates such as between December and April, representing a quarter year in which it is often convenient to have the data falling within that period tabulated and recorded aside from all other data. Another example is 80 that of amounts or numbers. At times, it is well to print data having numbers say between 500 and 800, or having amounts between 60.00 and 90.00, while not printing other data outside this range of numbers. So also in alphabetic control, it may be well at times to separate data including names beginning with K, L and M from 85 all other data.

To secure "between index" control over a range of names between two selected names comprising a plurality of letters, the machine may contain two banks devoted to name set-up knobs. The paired knobs of one bank may be set between the lowest letters in the scale and the letters spelling the one selected name lowest in the alphabet as, for example,—AAAAA and BROWN. The knobs in the other bank may be set to the highest letters in the scale and the other selected name highest in the alphabet as,—ZZZZZ and SMITH. The name data presented 100 to the machine would then be compared with the name set-ups in both banks, and the sorting, printing, accumulating, etc., control would be effected or disabled according to whether or not the name data fell within the range of control 105 selected.

It is an object that this control between two points should exercise all the same controls that have been explained above in connection with the control that was exerted on data below, 110 above and on a certain index. Such controls include printing during normal operations, while during total taking the functions of totalling and sub-totalling may be changed without printing under influence of the control devices. 115

An important object is to secure a selecting device that will separate out of a mass of data, a certain group of data, not alone of one characteristic but of a group of characteristics between variable limits set by the machine. Here- 120 tofore, in the knowledge of the applicant, selection depended upon a single characteristic of the data and only by later combining the results of single selection was group selection secured.

While the above outline of objects presents 125 the general purpose of the present invention many other worthy and novel purposes will be apparent as this specification continues.

The illustrative machine

To aid in describing this invention it has been thought advisable to apply it to a specific case. A certain class of machine has been illustrated in the drawings, a general outline of which machine will be given now to help the understanding 130 of the detail description given hereinafter. Even though this machine serves admirably to illustrate the important features of the invention it is to be understood that the specific application of these features is not intended to restrict their 135 use but that many variations and adaptations of the machine for use in other fields of business are contemplated.

A class of business has been chosen that it is 140 thought will best illustrate the practical use of the novel features of the invention. The machine illustrated is adapted for use by a large insurance company. It is thought that such a concern may have different districts each having a group of agents who solicit the disposal 145

of the various policies of the company to the public. Each district would have a machine such as that disclosed and also have a punch card system cooperating with the machine. This punched card system would require a key punch machine and operator for transferring the incoming data from the policies, etc. onto the punched cards. These cards would then be filed in accordance with a certain system. It will be assumed here that they are filed according to the kind of policy, each group of cards say of the same color being of the same type of a policy. These policies may demand different terms of payment, some annually, some quarterly, some monthly. The present machine will print bills or statements ready to mail calling for such payments.

The data recorded on the punched card is intended to cover most statistical requirements. 20 There is plenty of room left on the card, after the following data is on, for other records. The data on the card includes the following items:

A number given to the policy holder that distinguishes him from any other having the same name, etc. This number is a convenient means for sorting a particular record card out of a group of other record cards. A region punched to represent an amount is also on the card. This amount is the premium of the policy and requires 25 payment at intervals to keep the policy in force. If the amounts increase or decrease, a slight change in the layout of this machine would provide different spaces one for each amount which could be progressively printed as the policy 30 matures.

The age of the policy holder at the date of the taking out of the policy is recorded on the card mainly for statistical use. The agents are assigned numbers and these numbers are also recorded on the record card. The agent who is responsible for the taking of the policy is recorded by having a punching corresponding to his number inserted in a section reserved for it on the punched card. The occupation of the policy 35 holder is given one of a number of code numbers and punching corresponding to this number is cut in an appropriate portion of the record card. The code number of the key punch operator who transfers the data to the record card is represented by a combination of holes in the card. This designation is provided merely for placing the responsibility for mistakes made in making the record 40 cards. The date of the issue of the policy is also represented by a combination of holes on the card. This portion of the record is useful in governing the time of sending annual or periodical statements and for statistical purposes. The kind of policy is also represented on the card and may be used in sorting, aside from the card color differentiation. The full name and address of the policy 45 holder are also presented by code punchings on the card. These punchings provide the means for addressing the statements, besides furnishing means whereby an alphabetic listing of records according to name may be made or a listing according to location in a certain city or state is 50 possible. The convenience of having all this data on one card instead of on three or more cards is believed apparent. Thus, it is seen that a complete record of all information concerning a policy 55 is contained in a single record card.

Full printing facilities are incorporated in the machine for recording all the data mentioned above, as it is required. The group of punched cards upon which operation is desired is placed

into a feeding rack on the machine. From this rack they are fed down into cooperation with a jacquard device which utilizes all combinations of holes on the card to move type bars or actuators to an extent necessary to place a pair of type on the bar, corresponding to said combination, opposite two platens. Printing may then be performed on two record sheets. The one sheet is of the form of a bill and is cut off the supply roll and issued out of the machine after printing. This sheet is suited for mailing and may be sent out in a windowed envelope to the policy holder reminding him that a payment is due. The other sheet is in the form of a record strip and is kept in the machine, being wound on a storage roll after each printing operation. This strip is well suited for bookkeeping or statistical department use and may be removed from the machine for such use at any period, most likely at the end of every day. Means for no-printing, total printing, and other controls will be explained hereinafter. 80 85 90 95

There is a group of totalizers provided in the machine. The group comprises a separate totalizer for each of the 15 agents, and a grand totalizer. During regular operations the correct 100 agent's totalizer is automatically selected by a train of connections controlled by the movement of the agent typebar under control of the related combination of holes on the card. At the same time the grand totalizer is meshed simultaneously 105 with any one of the agent's totalizers. These totalizers are operated by rack teeth cut in the amount typebars which are also under control of a section of the punched card.

Thus, it is clear that during regular operations the totalizer operation and selection is wholly automatic and under control of the punched card. However, during totalling other conditions prevail. Only one totalizer at a time is engaged, and a blank card could be placed in 110 the jacquard device so that no selections are made by automatic means. A selection lever is provided for this purpose, and movement of it to one of the notched positions out of normal will select 115 one of the 15 agent totalizers or the grand totalizer for totalling. 120

During regular operations as the cards pass through the machine, an agent's totalizer will have accumulated on it the amounts standing on every card which contains the combination of 125 holes denoting that that particular agent wrote out the policy. Thus, as the bills are issued for the policies for which a certain agent is responsible, the amounts of those bills are accumulated in the related totalizer. 130

Number, totalizer, and sub-totalizer keys are provided to condition the mechanism meshing the totalizers with the actuators so that a total or sub-total operation of one of the totalizers can be secured. Upon depression of the total key, 135 movement of the selection lever to one of 16 positions, and subsequent operation of the machine, the total of the selected totalizer is printed and the totalizer is cleared. Movement of the selection lever also places a designation type in 140 position to print upon the record material, adjacent the item, the agent's number and a total sign showing that a total was taken. At the time of taking a total it would be well to place a blank card in the jacquard frame to prevent actuation 145 of all the feeler pins and movement of all unnecessary type bars.

In a similar manner, operation of the machine in combination with depression of the sub-totalizer key will produce a printed total of the amount 150

standing on a certain totalizer leaving the amount in the totalizer.

A non-add key is suited for use during regular operations of the machine. At such times as this key is depressed, printing may take place but accumulation of the amounts in the totalizer will be prevented. One use of this feature would be when follow up or duplicate bills are needed. The amount does not want to be added at this time for then it would be presented twice in the totalizer.

The uses to which the totalizers could be put are many. As shown in connection with the agent, they could be used to find the commission due the agent for his efforts in placing the policies. The amount on the totalizer, of course, is the amount billed the various policy holders secured by the agent, and his commission is only a percentage of the amount. As these commissions may diminish in percentage as the policy ages, only the policies secured by him over a certain period, usually say a year, may be selected at one time. These cards as they are selected (by devices about to be described) from others of their group (printing bills and a record meanwhile) will accumulate the amount over the certain period. This amount may be printed, and in crediting the agent, it may later be multiplied by the percentage of commission that the period calls for. So also, in a like manner, cards of another period may be selected and accumulated and later totalled from the agent's totalizer. This process may continue until up-to-date.

The operation may be carried on to determine the commission of 15 agents simultaneously and meanwhile the grand totalizer will record the sum amounts upon which the commissions for all agents are based. The agent's commission may also vary with the kind of policy. This condition could be taken care of exactly as the one above explained only selection of accumulation would depend on "kind of policy" rather than on date. When the commission is affected by two of the characteristics of a policy there can be two selections by two operations of the machine. The first operation could be non-add and merely selects required cards according to one characteristic. The next operation could select and add according to the other characteristic.

The above example of letting the totalizer represent an agent was chosen for its simplicity. There are many other uses to which they may be put in the machine perhaps to better advantage, but it is believed that the essence of the invention is fairly well illustrated when used as described. The totalizers may represent a kind of policy, a certain period of time, or even the policy holder. Many novel conditions would be brought about if the machine were provided with a large number of totalizers, each one representing a policy holder and being selected by the policy holder number. Then the amount accumulated on a totalizer would represent the amount paid on a policy, providing that all the bills issued by the machine were paid. If they were not paid, any follow-up system as now used would detect delinquents. Dividends, etc. could be figured from the amount held by the various totalizers.

At the front of the machine is located a control section. It consists of a control lever on one side and a control plate extending across the machine and having a plurality of notched slots along which knurled knobs may be shifted. The control lever is shiftable in a notched slot to one of

five controlling positions. Each position determines in what way the control knobs are to effect control of the accounting operations of the machine. Each control knob cooperates with a related type bar or actuator and has as many controlling positions as the type bar has printing positions, for example, the months control knob has 12 controlling positions. These control knobs are arranged in groups, each group being a separate characteristic of the data handled by the machine. For example, there are 5 amount control knobs, 3 date control knobs (year, month, day), 2 policy holders name control knobs, etc. It is contemplated that only one group of knobs be used for controlling at a time, although there is no reason why two or more groups should not be used as a simultaneous control. To aid in placing the control knobs in position, the slots in the control plate are notched and on the side of each notch are indicia identifying the position. So that once a certain number, name, or date is decided upon as a desired control, all that is necessary is to lift the related group of control knobs out of their inoperative position at the front of the control plate and move them to, and place them in, the notches corresponding to the number, name, or date selected. The knobs will remain in this position until moved by the machine operator for other control. In this position they are adapted to change the functioning of the machine in many ways, the one way in which they are to control at one time being determined by the control lever already mentioned. This control lever in one position (PRINT) disables the controlling action of the knobs so that printing accumulating, etc. will occur no matter what position the control knobs occupy.

In the next position "above index" of the lever the control is exerted on data whose magnitude in their respective scale is below that to which the control knobs have been set. For example, if the amount control knobs are set to \$3.69, and a card with an amount of \$3.75 is tendered to the machine, this data will be acceptable, and printing will occur in the normal manner. If the amount had been \$3.65, however, the controls would have functioned to prevent the printing of the data. In the same manner any other group of controls, say in the name or date scales, would have exerted their control on any data presented that was lower in their scale. The "exact index" position of the lever is one of decided utility. When the lever is in this position and the control knobs of a group are placed to represent an amount, name, date, etc. only the data including that certain amount, name, or date will be printed. For example, if Jan. 10, 1920 is set on the date control knobs, only data including that date will be printed. In the next position "below index" of the lever, the conditions described above in relation to the "above index" position are just reversed. For example, if SM be set on the name control knobs at this time, data including a name such as SLOSS will be printed but if a name such as SNOVER is presented, the data associated therewith will not be printed. The next position "NO PRINT" of the lever controls for preventing printing no matter what data is presented by the punched cards or in what position the control knobs rest. Another position, a control mechanism for which is shown in the drawings, could be added on the lever. It would control between two points set by two control knobs in a slot of any scale. For example, two knobs in the date scale could be set at Mar

and July, then operation of the machine would print only that data of a date between Mar and July. All others would be rejected.

These various controls above mentioned are very useful for statistical work in a large insurance business. A few of the examples of how the machine may be employed in such a business will now be given. The amount control knobs may be set to a certain amount and then with 5 the control levers in "exact index" position only policies having that certain premium will be listed, sorted, and accumulated, out of all others. The record furnished by using this control and setting up different amounts until all cards are 10 15 recorded would show which is the popular premium and which is second in demand, etc. Or, with the lever in "above index" position and the amount control knobs set to a certain amount, only policies having premiums larger than that 20 certain amount will be printed. All others will be merely fed through the machine. So also with "below index" control, only policies of smaller premiums than set up will be recorded. And with a "between index" control only policies having 25 premiums ranging between the amounts set up will be recorded.

With the age control knobs set to a certain age and the control lever in "exact index" position, only those policies having, in the data on 30 them, that certain age will be printed. All others will be discarded. If this control is used in conjunction with the date control the statistics can always be kept up to date regarding the age of policy holders, the age on the record card being 35 that of the policy holder when taking out the policy. The method to use would be, first, sort the cards according to date, giving a batch of cards for each year, say 1916, 1917, 1918, etc. Then, if the present date is 1920 and the 1917 40 batch of cards is being tabulated under an age control of 25, the real age of the people holding those 1917 policies is 28 years, and this fact could be considered in compiling the statistics.

With the "above index" or "below index" control being exercised, only policies in which the 45 holders are above or below respectively the age set up by knobs will be recorded. This control would be well employed in finding how many policies are outstanding to people in a dangerous 50 age, say above 85 years and below 9 years. The "between index" control would effect such a control also if the age control knobs are set to include a certain range of ages, say between 5 and 55 9 years. All policies allotted to children of that age would be recorded and all other policies would not be recorded.

If the agent's control knob be set in a certain 60 position and the machine operated under "exact index" control, only the policies secured by the certain agent will be recorded. If either the 65 "above index", "below index" or "between index" be used only policies secured by agents in the group respectively above, below, or between the setup will be recorded. This control will be especially useful if the agents are divided into 70 groups for competitive purposes, one group being matched with another in soliciting business.

The number assigned to each policy holder and 75 represented on the punched card may also be made useful in conjunction with the control mechanism. The data on the cards may be selected according to such a number or group of numbers. The policies may be numbered in the order of their issuance. Then, in conjunction with the date selection, there can be found and

tabulated the number of policies issued between certain dates, or in another case requiring the data of a certain group of policies between two policy numbers, after setting of the number control knobs, operation of the machine will record this information. 80

If the cards upon which mistakes have been made in transferring the data from the policy to the card are separated out of the main bunch of cards, means is provided for fixing the responsibility of such errors. A section on the card is allotted to record the key punch operator's number. The control section is provided with an operator control knob and means of selecting the cards of one or a group of operators for tabulation. So that out of the bunch of cards, the ones made by a certain operator may be selected and recorded, or the cards made by a certain group of operators may be separately recorded. 85 90

An occupation control knob is provided on the control plate and the punched cards are adapted to receive a combination of punched holes representing the policy holder's occupation. By means of these provisions the data on some of the cards because of having common occupational requirements may be selected out of the other data presented to the machine. Also, a group of occupations representing a common class of labor may be the determining factor in the selection 95 100 of data.

The date control may exercise very useful functioning in the machine. By this means the expired policies may be selected from the others. Periodical payment of the premiums may be insured by the control of the dating data over the 105 issuance of the bills. The annual paying policies could be selected according to the month of their issue. Say a policy was taken out on May 14, 1916, then a bill should be issued May 1, 1917, May 1, 1918, etc. That could be done in the machine by setting the date control knobs to control between May and June. Then, all policies dated in that class would be selected and tabulated and have bills printed. In a like manner, policies payable quarterly would be picked from 110 115 a group four times a year. 120

Say the quarterly policy is dated June 10, 1917 then on the date of Sept. 1, 1917, Dec. 1, 1917, and Mar. 1, 1918, etc. the date control knob will be placed at June position and the data on all 125 the June policies including the one above will be printed on a bill and a record strip, the amount will be accumulated in a totalizer and grand totalizer and the card will be sorted. To sort out and print a record of expired policies, 130 the control lever is set to "below index" and the date (20 or 30 years prior to the present date, according to kind of policy) is set up on the date control knobs. Then, out of the cards run through the machine, those below the set date, 135 in other words expired, will be tabulated, accumulated, and sorted from the rest. As shown, one control bank is provided for the year designation, giving control extending over 32 years. However, two banks may be assigned to this designation if a longer range of time control is 140 desired.

The "kind of policy" control may be utilized to sort the cards for placement in their proper office files. Two banks of controls are provided for this characteristic so that more than 900 different kinds of policies could be selectively controlled.

The "name" control is one that may have a multitude of uses. Only two banks of con- 145

tro's are shown devoted to this designation, as the first two letters of a name will generally place it in a group of names that is not too large. Where a large number of names are handled and many names differ only in the third or fourth letter, then additional controls should be provided as shown in connection with the "city" name. In the present machine, by setting the control lever to "exact" position and the name control knobs to AB, AC, AD, etc. successively, and running a bunch of cards through between each set up, an alphabetic listing of the names, plus the data associated therewith on those cards may be had. In the same manner a card containing a particular name may be picked out of a bunch of cards.

An address of a policy holder may determine selective control. The record card has provisions for street and street number printing, also space for city and state designation. The control section has "city" and "state" control knobs so that selection may be determined by geographical location of policy holders. With the "city" control knobs set in a formation of Boston and the control lever in "exact" position only the policies for holders residing in Boston will be tabulated. So also by means of the "STATE" control knobs a larger district, say, PENN., may be taken under control for recording.

From the above examples as applied to the insurance business only a few adaptations of this flexibly controlled machine may be observed. At any time during its operation and regardless of the position of the control knobs, printing or no printing may be had by setting of the control lever to either of those positions. The controls may also be used in combination where a plurality of characteristics of the data, any one of which is a desired controlling factor are wished to exercise control at the same time. An example of this would exist when there are set in controlling positions the control knobs for a certain agent and a certain date. Then not only would control be governed by the one characteristic, the agent, but the date of the data presented would also exercise control.

The ordinary total taking functions of this machine have been discussed above, but the machine is capable of other novel usefulness when totalling is done under control of the control section. This is accomplished by depressing an accumulator control key at the same time a total key is depressed.

When totalling is done under control it is possible to change, during operation of the machine, the function of totalling to a sub-total, or a sub-total to a total without printing a record, the change being made when the amount standing in the totalizer selected does not satisfy the control amount that is set up by the amount control knobs and the control lever. To take an example, let us say that the agent's commission is figured every month from the receipts of the month for which the agent is responsible, and that another condition is that no agent shall receive commissions on receipts of less than \$200, but that the amount of receipts, even though they are less than \$200, will be retained in the account of the agent for the next month when commissions will again be figured. To do this in the machine all that is necessary after shifting the selection lever to the position of the desired agent and depressing the total key is to depress the accumulator con-

trol key set up \$200 on the amount control knobs, position the control lever in "below index" position and operate the machine. Then, if that certain agent's totalizer contains less than 200 the item will not be printed but instead of a total being taken a sub-total will take place and the amount will be retained in the totalizer.

The control may also be exercised by the control of amounts above the set up amount. The agents may be rewarded by a bonus if receipts for a month are larger than \$3000. Also the size of the bonus will depend on the amount of the receipts over 3000. To retain all amounts over 3000 in the totalizers for later reference all that is required when totalling besides selecting the desired totalizer, depressing the total key, is to depress the accumulator control key, set up 3000 on the amount control knobs, put the control lever in "above index" position and operate the machine. If the amount in the totalizer is more than 3000 a sub-total will take place and the amount will remain standing on the totalizer wheels instead of being cleared out.

The way of changing the totalling functions as outlined above may also be used with the control lever in either "exact" or "between index" positions when a problem is presented for such a condition.

A control may also be had during sub-totalling for changing this function to totalling and clearing out whatever amount is in the totalizer. This control may also be of the forms "above", "below", "exact" or "between index". An incident of such a use follows:

We will assume that throughout the year the monthly receipts of the agents are recorded and punched cards made so that a tabulation may be made at the close of the year. At that time, after clearing the totalizers of the last month's receipts, all the receipts of the year are accumulated into the totalizer. It is assumed that any agent not doing business throughout the year of at least \$2,500 will have his agency taken away from him. With that purpose in view, the sub-total key is depressed, the selection lever is positioned and then the amount control knobs are set to 2,500, the control lever is put at "below index", the accumulation control key is depressed and the machine is operated. Upon operation, if the amount in the totalizer is less than 2,500 instead of a sub-total being taken as intended, the totalizer will be cleared to zero and so will be in condition to receive a new account. A record of agents to be retained for having their quota will be printed at the same time. With all the same conditions above in force, but the control lever in "above index" position, upon operation of the machine, a printed record of the agents to be discharged as not having over 2,500 will be secured the sub-total changing to a total in order to clear the totalizers containing more than 2500.

The machine may be employed in other classes or fields of business, for example, banking. Minor changes in construction may be necessary but nothing involving skill. We will take for a concrete example that 500 checking accounts are to be taken care of. The minimum amount allowed to stand in an account is to be \$200. If the account falls below this figure during the month a charge is to be made at the end of the month. Also, daily slips are to be printed indicating accounts overdrawn. Amounts will, of course, be added and subtracted at different times from the amounts in the accounts. At the end of every business day the amount standing in each account

is to be noted to detect overdrafts or accounts lower than \$200.

To meet these requirements, the machine would have 500 totalizers, one for each account, of a form as shown, connections being made from each totalizer to the amount racks. The means for controlling the totalizers may be punched cards as shown, or a keyboard may be provided for setting up the data. The printing and controlling sections may be used just as they are. During the day the amounts on checks drawn on a certain account are subtracted (by complements) from the related totalizer, while deposits made in the same account are added to the totalizer. At the end of a day or any period, all the overdrawn accounts will have an abnormally large amount standing on the totalizer, a figure such as 99,947 showing that the account has been overdrawn \$53. This defaultication can be noticed immediately when the check causing the overdraft is tabulated in the machine if the items printed on the record strip are noted through a window in the case. But if desired, at the end of the day a printed list and printed sheets of all overdrawn accounts may be had at once.

To do this, the amount control knobs are set at 90,000, the control lever is set at "above index", the accumulator control key and sub-total key are depressed and the machine is operated between successive selections of the totalizers. Then, as sub-totals are taken of the different totalizers, if one comes along upon which more than \$90,000 is present, the control will be exercised and will print an extra slip and change the sub-total to a total, clearing that totalizer. If desired, the sub-total may be taken and the amount left in the totalizer (even though control is exercised) by not depressing the accumulator control key. After all 500 accounts have been selected, the overdraft slips may be gathered and noted and used as notices to the account holder, of the state of his account.

Now, we also wish to detect any account having less than \$200 registered in a related totalizer at the end of a day. To do this the amount control knobs are set to \$200, the control lever is put in "below index" position, the sub-total key is depressed, and the machine is operated between successive selections of the different totalizers. Any account that has less than \$200 will then effect the printing of a slip. The slip will, of course, have imprinted upon it not only the amount standing in the totalizer but also a designation (by number or name) of the totalizer selected.

In the making of monthly statements the machine may also be useful. We will assume that the old balance is recorded at the head of a new statement sheet with the designation of the account. This can be done at the end of a month by the machine set to take an ordinary sub-total. At the end of the first day in the month the old balance is noted and the amount set up on the control knobs, the control lever is moved to "exact" position, the related totalizer is selected, sub-total key depressed, and the machine operated.

Every totalizer containing an amount similar to its old balance will print a slip showing that no transactions in the related account have been made during the day. If no slip is printed, however, the control lever should be moved to either "above index" or "below index" until a slip is printed. This slip will show a difference of the account over the old balance and this difference

may thus be noted on the statement sheet. With few changes the machine disclosed could be made to no-print the amount if it is exactly the same as the old balance and print the amount when it is different. Another change would allow the use of the statement sheet as an inserted slip so that printing of change in account would be done directly on the statement. These two changes would increase the speed of making a statement record.

In government work also there are many conditions where use may be made of the novel features herein disclosed. This may include payroll, census and statistical work. The statistical work would involve examples somewhat like those given above in adapting this invention to an insurance business. The census tabulations would be expedited in no small measure by the ability of this device to simultaneously pick out any one of a select group of characteristics for tabulation. For example, recording of data concerning people between ages of 10 to 20 or 20 to 30, etc. or data relating to manufacturing establishments having a capital between \$50,000 to \$60,000, etc. the data can be selected, printed and sorted simultaneously and does not necessitate separate selection for each characteristic. Tabulation according to each individual characteristic can be had, of course, when desired.

In large stores having merchandise that is sold on the installment plan many uses of the present machine may be developed. For example, a totalizer may be assigned to each opening installment account. The totalizers may be grouped according to the amount, all the totalizers in a group being supposed to receive the same amount every month. As installments are paid they are added in the totalizer. The bills requesting the installment payments may be made in a manner similar to the insurance bills noted above. When the amount in the account falls below the required standing of the group, the control mechanism in "below index" position will control printing to issue the bill.

The above portion of the description is a general outline of some of the objects of the invention and uses of the machine. The several sections of the machine will now be described in detail with reference to the drawings which accompany and form part of the specification.

Fig. 1A is a side elevation view of the forward portion of the machine showing the operating connections for the printing, controlling and paper feeding mechanisms.

Fig. 1B is a continuation of Fig. 1A and is a side elevation view of the rear portion of the machine showing the card feeding, sensing and sorting mechanisms, also the motor and connections to the operating mechanism for totalizer engagement.

Fig. 2 is a view of a perforated record card. It is perforated as a card would have to be in order to actuate the machine and print a record as shown in Fig. 13.

Fig. 3 shows the different combinations of holes possible with five holes in combination. It also shows the number of steps of movement given the actuators of the machine, and the corresponding alphabetic and date printing positions of the actuators for each combination of holes.

Fig. 4 shows the different combinations of holes possible with four holes in combination. It also shows the number of steps of movement given the actuators of the machine for each combination of holes.

Fig. 5 is a side elevation view of the mechanism for converting the depression of four rods, in a jacquard mechanism sensed by four holes in a card in different combinations, into 16 different extents of movement of a type bar and totalizer actuator.

Fig. 6 is a side elevation view of the mechanism for converting the depression of five rods in different combinations into 32 different extents of movement of a typebar containing letters, dates, or numbers.

Fig. 7 is a side elevation view showing the arrangement of three of the mechanisms shown in Fig. 5 so as to be able to operate all three from a single bank of 12 rods in the connection box of the jacquard mechanism.

Fig. 8 is a side elevation view showing the arrangement of two of the mechanisms shown in Fig. 6 so as to be able to operate both from a single bank of 10 rods in the connection box of the jacquard mechanism.

Fig. 9 is a side elevation view of the control and printing mechanisms.

Fig. 10 is a detail view of a form of control construction for setting up two control characteristics.

Fig. 10a is a detail view of another form of manipulative control setting devices.

Fig. 11 is a sectional detail view taken along line 11-11 in Fig. 9 and showing the type bars and platens in printing position.

Fig. 12 is a sectional view of the platens and the platen raising and lowering mechanism.

Fig. 13 is a sample of a statistical record sheet printed by the machine.

Fig. 14 is a sample of the detail strip retained in the machine.

Fig. 15 is a sample bill issued by the machine.

Fig. 17 is a plan view of the control plate and manipulative knobs showing the controlling positions of the knobs.

Casing and framework

In Figs. 1A and 1B there is shown one side of the main frame of the machine which serves to support most of the various mechanisms to be described. This frame is composed of right side frame 50 and a left side frame 51, each near its respective side of the machine. The space between the frames may be provided with intermediate bracing frames if additional support for the cross shafts and bars is desired. Many of the cross shafts use the two side frames for bearings while other shafts and bars are fixed in the frames and act as tie rods. The two vertical frames are secured to and supported by a base plate 52.

The machine is constructed so that the bulk of the operating parts are located between the two side frames 50 and 51, although at each side there is an overhang of certain portions of the mechanisms including a number of the main through shafts. It will be apparent as the description progresses that wherever possible the various distinct features of the machine have been constructed as individual units having their own supporting frames which are separably mounted and secured in place on an appropriate portion of the main supporting structure.

The frames 50 and 51 extend at the rear (Fig. 1B) to support the card feeding, sensing, and sorting mechanisms mounted on the rear of the machine.

A casing 53 covers most of the machine leaving an open space for the insertion of the record cards. The case also has apertures through which the controlling keys are depressed and the levers are rocked. A hinged cover plate 54 in the case when lifted gives access to the record material which may then be removed and replenished.

Main operating mechanism

In the following description the operating connections will be traced from the power source up to the point of application. The application of the driving parts will be described further on in connection with the mechanism with which they are used. Mounted on the base 52 is an electric motor 55 (Fig. 1B) the shaft 56 of which extends into a gear reduction unit 57. This gear reduction device may consist of the usual worm on the motor shaft with a cooperating worm wheel. Connected to the worm wheel is one side of a clutch, the other portion of the clutch being attached to a drive shaft 58. The clutch is housed in a portion 59 of the frame 57.

Although not shown, it is assumed that all the usual adjuncts of the above mentioned operating devices will be furnished, such as a switch for the motor, an operating bar for the clutch which may be held down for continuous operation of the machine or touched for single operations of the machine, and an interlock preventing operation of the clutch during operation of a controlling key or vice versa. Also attached to the drive shaft 58 is a gear 60 and a chain sprocket 61. The gear 60 is in mesh with a gear 62 and actuates this gear through a single revolution on each operation of the machine. The gear 62 then transmits its motion to similar sized gears 63, 64, and 65, that contain operating cams and projections for actuating the various devices shown in Fig. 1B. For the purpose of transmitting the motion of the operating shaft to the front of the machine a chain 66 is secured around sprocket 61 from which it runs forward to a sprocket 67 (Fig. 1A), loosely mounted on a stud 68 in side frame 50. Attached to the sprocket 67 is a gear 69 having a cam groove for operating the control mechanism. This gear 69 is in mesh with another gear 70 which is loosely pivoted on a stud 71 in the right side frame. Gear 70 has attached thereto a cam 72 for operating a preliminary control device; also attached are two mutilated gears, the gear 73 has a single group of teeth 74 for operating the printing mechanism, the other gear 75 has two groups of teeth 76 for actuating the paper feeding devices.

Card handling devices

The following section of this specification deals with the means for holding, feeding, sensing and sorting the record cards employed in the machine.

A box 77 (Fig. 1B) is secured to the rear extensions of the side frames 50 and 51. Fastened in the box is a shelf 78 upon which resets the record cards 79 and a follow up weight 80. The weight 80, by means such as a spring or weighted pulley, keeps the record cards before its face frictionally held against a plate 81. Between the plate 81 and the shelf 78 is an open space through which only one card may pass at a time. When fed through this space the card falls into the sensing mechanism between plate 81 and a pin frame 82 where the card is supported upon a pawl 83.

A train of operating parts are driven by the main operating mechanism. They are used for the purpose of feeding a card from the holding devices into the sensing mechanism.

- 5 Mounted on the side of the gear 63 is a pin 84 which upon every revolution of the gear 63 acts upon the cam face of a lever 85 to rock the lever in a clockwise direction. The lever 85 is fastened to a shaft 86 which has a bearing in the side frame 50 and extends through to the inside of the machine. On the inside of the machine an arm 87 is fastened to shaft 86. At the end of the arm is pivoted a link 88 which serves as a connection to a long lever 89 which is pivoted on a shaft 90. A spring 91 stretched between lever 89 and a stud on the side frame serves to hold the parts in normal position. Operatively connected to the end of lever 89 by a pin and slot connection is a sliding pawl 92 which has a short finger overlying the record card that is next to the plate 81. The pawl 92 is suitably held on the plate 81 so that it may slide vertically down the plate and carry before it a record card. From the above description it will be apparent that every time the machine is operated the lever 89 will be oscillated, sliding the pawl 92 down the plate 81 and feeding a card into the sensing mechanism. After the pin 84 passes the high point on the cam face of lever 85, the spring 91 restores the parts, lifting the pawl 92 so that its finger overlies the next record card in the pack on the shelf 78.

A sensing mechanism is provided for the purpose of operating a jacquard device in accordance with the holes punched in code on the record card. By means of this mechanism the holes in the card are adapted to determine which of the rods in the jacquard device will be operated.

- 40 A pin frame 93 extends across the machine between the frames 50 and 51. In the pin frame are flexibly mounted a plurality of rows of sensing pins 94. Each of the pins is provided with a spring (not shown) which holds the pin extended out of the frame 93. Rollers 95 are mounted on the sides of the pin frame for supporting it in slots 96 on the insides of side frames 50 and 51. The slot is longer than the distance between the rollers on the frame, thus allowing the frame to reciprocate back and forth horizontally. To operate the connections for reciprocating the pin frame, a cam groove 97 is cut in the side of gear 63. A bell crank 98 is pivoted on a stud 99 and has on the end of one arm, a roller which protrudes into the cam groove 97. In a rotation of the gear 63 the bell crank 98 will be oscillated first in a counterclockwise direction and then in a clockwise direction back to normal position. This motion of the bell crank is transmitted to the pin frame by a link 100 extending between the vertical arm of the bell crank and an arm of a lever 101 pivoted on a stud 102 in the right side frame. The other arm of the lever 101 is slotted to receive a roller 103 on the pin frame 93. By means of the above connections, it is plain that during the early part of the movement of gear 63, pin frame 93 will move towards the record card held between plates 81 and 82, and during the final portion of the rotation of gear 63, the pin frame will withdraw the pins from the card.
- 45 When the pin frame moves towards the card the sensing pins will sense the card and wherever there is a perforation in the card the pin will reach through and move the related connection rod *a*, *b*, *c*, etc., in the jacquard frame. If an unpunched portion of the card is presented be-

fore a sensing pin it will be obstructed and the spring in the frame 93 will be compressed and the related connection rod *a*, *b*, or *c* will not be moved. After the card is sensed and the pins 94 are withdrawn from the card, the latch 83 is withdrawn allowing the card to fall into a sorting bin.

The above section of the specification is concerned with the card handling devices of the machine so now at this point in the specification the card as it is punched for use in the machine may very well be described.

Fig. 2 shows a sample record card 79 of regular commercial size which is punched in the code required by the jacquard mechanism in the present invention. The specific punching shown is that which is necessary to control the machine so that the statistical sheet shown in Fig. 13 is printed. It will be noted that the groups of holes on the left hand side of the card are four holes in height and that three groups of holes may be placed one above the other, each group using four of the twelve holes in the vertical rows. The four holes in a vertical row are adapted to control the positioning of an actuator in one of 100 16 positions. The groups of holes on the right hand side of the card are five holes in height and two groups may be placed one above the other with a horizontal space between.

In Fig. 2 the space allotted to a related group 105 of holes is encircled with a fine line. These groups will now be named and numbered. The amount group 117, the age group 118, the agent group 119, and the number group 120, are shown on the left hand side of the card. The operator 110 group 121, the date group 122, the first name group 123, the last name group 124, and the state group 125 are on the upper right hand side of the card, while the occupation group 126, policy number group 127, street number group 128, street 115 name group 129, and city group 130 are on the lower right hand side.

If desired the data may be printed on the card at the time it is punched. This would obviate the necessity of decoding the combinations on the card when it is required to read the card as is sometimes done in certain classes of work.

Fig. 4 shows all the different combinations of four holes which may be punched in the card, with the corresponding actuator position lettered 125 below each combination. There are sixteen actuator positions, providing room for a zero type and one to fifteen type on the printing portion of the actuator. The totalizer operating portion of the actuator will be adapted to rotate the totalizer wheel through fifteen steps of movement. Of course, this much movement is not always needed. In the English money system using pence, eleven steps of movement are needed, while the American money system or the decimal system, requires only nine steps of totalizer wheel actuation. So it is apparent that the number of steps of actuator movement are more than enough as far as totalizer actuation is concerned. The connection rod designating letters *v*, *x*, *y*, and 130 *z* have been placed in line with the holes with which the related rod would cooperate on a card.

Fig. 3 shows all the different combinations of five holes which may be put on the card, with the corresponding actuator position lettered 145 below each combination. These actuators as shown in the present machine are used to position a type section and not to actuate a totalizer although they may be used to do so if desired. There are thirty-two actuator positions, provid- 150

ing room for a blank type and one to thirty-one type on the printing portion of the actuator. This printing capacity just meets the requirements of printing the day of the month in date printing. 5 Of course, the printing capacity is more than that required for printing the 26 letters of the alphabet and the 12 months of the year. These various date, number, and alphabet type are shown in Fig. 3 in vertical alignment with the combination of holes necessary to secure their selection for printing. The letters *a*, *b*, *c*, *d*, and *e* have been placed in horizontal alignment with the perforations with which the related connection rods cooperate.

15 *Jacquard or decoding mechanism*

It may be noted from the description of the record card that there are disclosed herein two forms of this jacquard device. One is under the control of combinations of four holes and the other form is under the control of five holes. In both forms the same principle obtains and this principle may be expanded to employ the use of more than five holes in combination. In 20 the illustrative showing the two forms of jacquard devices are used and they are provided with a common connection box for housing the connection rods *a*, *b*, and *w*, *x*, etc., previously mentioned.

30 This connection box (Figs. 5, 6, 7, and 8) comprises spacing plates 131, 132, 133, 134, and 135 in which are the holes for guiding the connection rods. These plates are held in place by two side plates 136, only one of which is shown in Fig. 5, and a center plate 137, Fig. 6. The connection box is removable as a unit. It is contemplated that the side plates have fixed lugs or studs for sliding in locating slots in the main side frames. The box could slide out of the back of the machine after the removal of the sorter and sensing devices.

In Fig. 5 is shown the form of mechanism controlled by four punched holes in combination on a record. The view is a section showing one bank 45 of the connection rods with the mechanism cooperating with the four top rods which cooperate with the holes in the amount group 117, Fig. 2 on the record card 79. Each of the rods *w*, *x*, *y*, and *z* has a spring 138 for restoring it to normal position and a stop 139 for holding it there. When a sensing pin 94 is inserted through a hole in the record card it will slide the related connection rod to the left in Fig. 5. The left end of the connection rod then pushes upon a stop pawl which normally holds a rack from movement. There are two layers of such stop pawls cooperating with each bank of four rods. The parts throughout the device for the one bank are confined in the plane of these two pawls. A thin 55 spacer 140 is provided between adjacent pawls and racks to space and guide them in their movement.

When the rod *w*, Fig. 5, is operated it rocks the pawl 141 pivoted on the shaft 142 which extends 35 between the main side frames. This pawl 141 normally abuts the end of a rack 143 slidably mounted on a rectangular bar 144 that extends between the side frames. A pair of combs 145 fixed to the bar, guide the rack and hold it in 40 vertical position.

The end of the slot in rack 143 is exactly one tooth space of the teeth on the rack, away from the side of the comb 145 so that at the proper time if the pawl 141 is rocked out of the path the 45 rack 143 will move one tooth space to the left.

In a similar fashion operation of rod *y* will rock a pawl 146 also pivoted on shaft 142 and separated from pawl 141 by spacer 140. This pawl 146 cooperates with rack 147 alongside of and somewhat similar to rack 143 the only difference being that the end of the slot in rack 147 is two tooth spaces away from the side of comb 145.

The operation of rod *x* or rod *z* produces a somewhat different effect. A pawl 148 pivoted on a shaft 149 has pivotally mounted on one end a bell crank 150 one arm of which abuts the end of rod *x* while the other arm is in front of rod *z*. Thus, it is apparent that if either rod *x* or rod *z* is operated alone the bell crank 150 will rock about the end of the other rod as a fulcrum and in turn rock pawl 148 half the distance that it would be rocked were both rods *x* and *z* operated simultaneously. Thus it is clear that pawl 148 can be rocked to two extents, a small angle of movement by operation of one rod and a larger angle of movement when both rods are moved together. The horizontal arm of pawl 148 reaches to the right of shaft 149 and cooperates with a rack 151 slidably mounted on a rectangular bar 152. Both bar 152 and shaft 149 are mounted 100 in the main side frames. The rack 151 is almost entirely hidden by a somewhat similar rack 153 which is in front of it in Fig. 5. The end of the slot in rack 151 is eight tooth spaces from the comb on bar 152 so that if released for movement 105 it can slide that far. But, if pawl 148 is only rocked the small amount, it will, upon movement of the rack engage an extension 154 on rack 151 and only allow the rack to move four steps instead of eight. The eight steps of movement of 110 rack 151 are only allowed when the pawl 148 is rocked the larger amount by joint operation of rods *x* and *z*.

Another pawl 155 is offset to the side of crank 150 and is adapted to be operated by rod *z*. This 115 pawl also pivots on shaft 149 and has a forwardly extending arm normally abutting the end of a rack 153 which has a slot guiding it on bar 152 and allowing it to move four tooth spaces. It will be noticed that operation of rod *z* alone 120 will rock both pawls 148 and 155 releasing racks 151 and 153 so that each may move four steps.

A pair of bars 156 and 157 extend between the main side frames. Upon these bars there are 125 fixed leaf springs 158 and 159 that have extensions bearing upon each pawl tending to keep the pawl in normal position.

Extending alongside the pawls 148 and 155 is a shaft 160 which is mounted in bail arms 161 that are fixed to each side of shaft 149. A slight 130 clockwise movement of shaft 149, will, through the above devices, swing the ends of pawls 148 and 155 out of the path of racks 151 and 153. This occurs only during total taking and will be described more fully further on in the specification. In a similar arrangement shaft 162 and bail arms 163 pivot on shaft 142 and are connected to bail arm 161 by a link 164. Thus, pawls 141 and 146 are rocked to release racks 143 and 147 135 simultaneous to the release of racks 151 and 153. 140

For the purpose of restoring and governing the time of movement of the four racks 143, 147, 151, and 153, there is provided a restoring bail. This bail consists of two arms 165, fixed to shaft 166 having two shafts 167 and 168 extending between them. A counterclockwise movement of shaft 166 will move arms 165 to the left (Fig. 5) 145 rocking shaft 167 away from racks 151 and 153 and shaft 168 away from racks 143 and 147. Subsequent clockwise movement of shaft 166 will 150

restore all the racks to their normal position. The shaft 166 is mounted on bearings in the two main side frames and extends from the right frame for operation.

5 The operating connections for the bail are shown in Fig. 1B. The shaft 166 extends from the side frame and has fixed to its end an arm 160' to which are attached two links 161' and 162' the one link 161' serving to connect the 10 various shafts 166 together and the other link forming an operating connection to an oscillating bell crank 163'. The other shafts 166 have secured thereon arms 164' to which link 161' is pivotally connected. The crank 163' is operated 15 by a box cam 165' on gear 64 by means of a roller 166' on one arm of the crank which extends into the groove of said cam.

From the above we may gather that there are 20 four racks under control of a bank of four rods and that each of the racks has a different extent 25 of movement, namely, one, two, four, and eight steps of movement. It is noted that each extent of movement is a factor in the largest number of steps of movement possible with four record 30 characteristics in combination. This novel principle is discussed further on in connection with the five hole combination in the record card.

The devices about to be described are for the 35 purpose of summing up or adding together the simultaneous movement of any number of the four racks and imparting this movement to a single actuator. These devices are adapted to transmit the movement of a single rack or movement of any combination of the four racks to an actuator.

For the purpose a novel form of differential 40 gearing is employed. A pinion 169 (Fig. 5) meshing with opposite racks 143 and 153 is pivotally mounted by a stud 170 on a rack slide 171. A similar pinion 172 meshing with racks 147 and 151 is similarly mounted on another rack slide 173. These rack slides are held in place and slide 45 on rectangular bars 174 and combs 175 between frames 50 and 51.

It is apparent that the pinions may rotate or slide without rotating or have a combined sliding and rotating movement. If rack 143 is held immovable while rack 153 moves four tooth spaces then pinion 169 will have a combined movement 50 and will rotate two tooth spaces, meanwhile sliding two tooth spaces to the left carrying slide 171 along. If rack 153 does not move while rack 143 moves one tooth space then pinion 169 will rotate and carry slide 171 to the left one-half a tooth space. If both racks move for the first 55 tooth space of movement pinion 169 will not rotate but will slide with rack slide 171 one space to the left, when rack 143 is stopped and rack 153 continues to move three more steps the pinion 60 will again have a combined motion of one and one-half steps of rotation and one and one-half steps of sliding. From the above it is clear that whatever the combined movement of racks 143 and 153 rack slide 171 is moved exactly one-half 65 C3 that amount, namely, zero, one-half, two or two and one-half tooth spaces.

In a similar way rack slide 173 will have imparted to it through pinion 172 exactly one-half the combined movement of racks 147 and 70 151. Therefore rack slide 173 will move zero, one, two, three, four, or five tooth spaces to the left.

It is noted that rack slide 173 has a depending 75 arm 176 which is provided with rack teeth opposite to the rack teeth on the end of slide 171.

A pinion 177 cooperates with the rack teeth on rack slides 171 and 173 in a manner similar to the cooperation of pinion 169 on 172 with the racks 143, 153. This pinion 177 is pivotally mounted on the end of a rack slide 178 which is guided vertically and horizontally by the bars 179 and combs 180 between frames 50 and 51. A tension spring 181 between a fixed rod 182 and the end of rack slide 178 urges the rack slide 80 to the left (Fig. 5).

The tension in this spring is transmitted through the rack slides and pinions over to the four racks, urging them to the left and moving them when the pawls and bail 165 allow. Since the relation between rack slide 178 and rack slides 171, 173 is the same as the previously described relation between rack slide 171 and racks 143, 153, it is believed apparent that rack slide 178 will receive exactly one-half the combined movement of rack slides 171 and 173. And since the movement of slides 171 and 173 is only one-half the original combined movement of the four racks, it is clear that rack slide 178 is moved to the left one-fourth of the combined amount that the four racks are permitted to move. This movement is one-fourth of zero to fifteen tooth spaces, or zero to three and three-fourths tooth spaces on rack slide 178. So that now if we multiply the movement of rack slide 178 four times, a single member will have a movement equal to the combined movement of the four racks. That is the purpose of pinion 183 and segment 184.

A shaft 185 fixed in the main side frames has loosely mounted thereon, a pinion 183 to which is attached a segment 184, the gear teeth of which 100 are formed on a pitch circle four times the diameter of the pitch circle of the pinion. The gear teeth of pinion 183 mesh with rack teeth 186 on rack slide 178 so that movement of rack slide 178 to the left will rock segment 184 115 in a clockwise direction. This movement of segment 184 is transmitted to an actuator slide 187 by means of rack teeth 188 on the slide. Thus, it is clear that the actuator 187 receives a movement of zero to fifteen steps depending 120 upon the combination of rods *w*, *x*, *y*, and *z* operated.

These actuators 187 have many uses in the machine that are explained as the specification continues. Since they are the amount actuators 125 they have rack teeth 189 for actuating the totalizer. Other rack teeth 190 are provided for holding the racks while totals are being taken. These rack teeth could also serve in connection with a detent for giving the actuators a final adjustment for printing alignment. However, there is shown cooperating with the teeth 190, a pawl 191 which is loosely pivoted on a shaft 192 with an attached spring 193 tending to engage the pawl with the rack teeth. A bail fixed to shaft 135 192 consisting of arms 194 and a cross rod 195 normally holds the pawls out of engagement with the rack. On every operation of the machine and at the proper time during the taking of a total, the bail allows the pawls to rock into engagement with the rack by the following means. The shaft 192 extends beyond the right side frame 50 (Fig. 1B) and has an arm fixed to its end. A link connects this arm to the midpoint of a lever 196 pivoted on the side frame and carrying a roller which cooperates with a cam face 197 cut on the side of gear 65. A spring 198 (Fig. 5) connected to bail 194, serves to keep the roller in constant cooperation with the cam 197. This cam is so proportioned that after the actuators 140 150

187 have been adjusted the pawls 191 engage the teeth 190 and prevent further movement of actuators 187 to the right. The actuators may be moved to the left, however, for then the pawls 191 merely ratchet over teeth 190.

5 The form of jacquard device under the control of five holes in combination on a record will now be described. The connection rods *a*, *b*, *c*, *d*, and *e* (Fig. 3) for this device are mounted in the same 10 connection box discussed above, the relative position of the rods being obvious from the position of the holes in the record card, (Fig. 2). As the construction and mode of operation of this jacquard device is quite similar to the one already 15 discussed, the description is not given in detail.

In Fig. 6 is shown the form of mechanism controlled by five holes in combination on a record. The view is a section showing one bank of the connection rods with the cooperating mechanism. 20 The rods have springs 138 for restoring them to normal position. The left end of the connection rods cooperate with stop pawls that normally hold racks from being moved. There are two 25 thicknesses of stop pawls cooperating with each bank of five rods as in the case of the four rods. The pawls are offset over or under each other to 30 keep within the two thicknesses of space. The spacers 140 shown in Fig. 5 may also be provided to guide and space the racks and pawls in Fig. 6.

35 When the rod *a* (Fig. 6) is operated, it rocks a bell crank 200 which is pivoted on a stop pawl 201 that is mounted on shaft 202. This bell crank 200 has a short arm cooperating with rod *a*, and 40 an arm twice as long cooperating with rod *d*, so that when movement of rod *a* rocks the crank using the end of rod *d* as a fulcrum, pawl 201 will be pushed twice as far as when rod *d* rocks, the crank with the end of rod *a* as a fulcrum, thus giving a stop pawl 201 two different extents 45 of movement according to which rod is operated. This pawl will get a third and still further extent of movement when both rods *a* and *d* are operated together. Stop pawl 201 normally abuts the end 50 of a rack 203 slidably mounted on a rectangular bar 204 that extends between the main side frames. A pair of combs 205 held on the bar 55 guide the rack and hold it in vertical position. The end of the slot in rack 203 is exactly three tooth spaces of the teeth on the rack away from the side of the comb 205 so that if the pawl 201 is rocked completely out of the path of rack 203, it will be able to move three tooth spaces to the left.

60 However, stop pawl 201 does not always rock completely out of the path of the rack but has three extents of movement; rack 203 has a shoulder 206 allowing it to move one tooth space when pawl 201 is rocked a slight extent by rod *d*, and a shoulder 207 allowing it to move two tooth 65 spaces when pawl 201 is rocked by rod *a*. When pawl 201 is rocked still further by operation of both rods it completely clears the rack allowing the rack to move until the end of the slot abuts comb 205.

65 The operation of rod *b* rocks a stop pawl 208 that is also pivoted on shaft 202. This pawl 208 normally prevents movement of a rack 209 which is slidably mounted next to rack 203 on bar 204. The slot in rack 209 is long enough to permit 70 a movement of four tooth spaces.

75 The operation of rods *c* or *e* produces a somewhat different effect. A pawl 210 pivoted on shaft 211 has pivotally mounted on the end of one of its arms a bell crank 212, one arm of which abuts the end of rod *c* while the other arm is in

front of rod *e*. It is apparent that if either rod *c* or rod *e* is operated alone the bell crank 212 rocks about the end of the other rod as a fulcrum and rocks pawl 210 half the distance that it would be rocked were both rods *c* and *e* operated simultaneously. Thus it is clear that pawl 80 85

210 can be rocked to two extents, a small angle of movement by the operation of one rod and a larger angle of movement when both rods are moved together. The upper arm of pawl 210 reaches to the right of shaft 211 and cooperates 90 with the end of a rack 213 slidably mounted on a rectangular bar 214. Both bar 214 and shaft 211 extend between the main side frames. The end of the slot in rack 213 is sixteen tooth spaces 95 from the comb on the bar 214 so that if released for movement it can slide that far. But if pawl 210 is only rocked the small amount it will, upon movement of the rack, engage an extension 215 on rack 213 and only allow the rack to move eight 100 steps instead of sixteen. The full sixteen steps of movement of rack 213 are only permitted when the pawl 210 is rocked the larger amount by joint operation of rods *c* and *e*.

Another pawl 216 is offset to the side of crank 100 212 and is also adapted to be operated by rod *e*. This pawl also pivots on shaft 211 and has a forwardly extending arm normally abutting the end of a rack 217 which has a slot guiding it on bar 214 and allowing it to move eight tooth spaces. 105 It is noted that operation of rod *e* alone rocks both pawls 210 and 216, releasing racks 213 and 217 so that each may move eight steps.

For the purpose of restoring and holding the pawls in normal position there are provided two 110 fixed rectangular bars 218 to which are fastened leaf springs 219 having extensions bearing upon the pawls.

A bail similar to the one described in connection with the mechanism in Fig. 5 is provided 115 for the purpose of restoring and governing the time of movement of the four racks 203, 209, 213 and 217. This bail consists of two arms 220 fixed to shaft 166, which may be a continuation of shaft 166 (Fig. 5) or connected thereto. Two shafts 120 211 and 222 extend between the arms 220; shaft 221 cooperates with racks 213 and 217 and shaft 222 cooperates with racks 203 and 209. Since the operation of this bail is the same as bail 165 (Fig. 5) no further explanation of its operation 125 is thought necessary.

Considering the device as far as it is described, it is noted that there are four racks under control of a bank of five rods and that each of the racks has a different extent of movement. One 130 rack can move from one to three steps while the other three racks are capable of four, eight, and sixteen steps of movement respectively. Operation of each rod causes one, two, four, eight, and sixteen steps of movement respectively.

The devices about to be considered are for the purpose of summing up or adding together the simultaneous movement of any number of the four racks and imparting this movement to a single actuator. These devices are adapted to 140 transmit the movement of a single rack or movement of any combination of the four racks to the actuator. In view of the similarity between these devices and those described above in connection with Fig. 5, only a brief description is given.

145 pinion 223 (Fig. 6) meshing with opposite racks 209 and 213 is pivotally mounted by a stud 224 on a rack slide 225. A similar pinion 226 meshing with racks 203 and 217 is similarly mounted on another rack slide 227. These rack 150

- slides are held in place and slide on rectangular bars 228 and combs 229 between frames 50 and 51. Rack slide 225 is moved to the left one-half the combined movement of racks 209 and 213, 5 namely, zero, two, eight, or ten tooth spaces. Rack slide 227 will move due to cooperation with racks 203 and 217, zero, one-half, one, one and one-half, four, four and one-half, five, or five and one-half tooth spaces to the left.
- 10 Rack slide 227 has a depending arm 230 which is provided with rack teeth opposite to the rack teeth on the end of slide 225. A pinion 231 cooperates with both racks in a manner similar to the cooperation of pinion 223 with racks 209 and 213. This pinion 231 is pivotally mounted on the end of a rack slide 232 which is guided by bar 233 and combs 234. A tension spring 235 between a fixed rod 236 and the end of rack slide 232 urges the slide to the left (Fig. 6). Through the 15 various connections this spring urges the four racks to the left and moves them when they are released.
- 15 From the above explanation it follows that rack slide 232 is moved to the left one-fourth of the combined amount that the four racks are allowed to move. This movement is one-fourth of zero to thirty-one tooth spaces or zero to seven and three-fourths tooth spaces on rack slide 232. This movement is multiplied four times by the 20 following means.

20 A shaft 237 fixed in the main side frames has loosely mounted thereon a pinion 238 to which is attached a gear 239 the teeth of which are formed on a pitch circle four times the diameter of the 25 pitch circle of the pinion. The gear teeth of pinion 238 mesh with rack teeth 240 on rack slide 232 so that movement of rack slide 232 to the left will rock gear 239 in a clockwise direction. This movement of gear 239 is transmitted to an actuator 30 slide 241 by means of rack teeth 242 on the said slide. Thus it is apparent that the actuator 241 receives a movement of zero to thirty-one steps depending upon the combination of rods 25 a, b, c, d, and e, that are operated. These actuators 241 carry the alphabetic, date, etc. type and have other uses that will be described further on in this specification.

25 In Figs. 7 and 8 are shown views of typical sections through full banks of the jacquard device. In Fig. 7 the dotted outlines enclosing the large numerals 5 represent the spaces occupied by the mechanisms shown in Fig. 5 and the dotted outlines enclosing the large numerals 6 (Fig. 8) represent the places occupied by the mechanisms 30 shown in Fig. 6. These mechanisms are not shown in detail in Figs. 7 and 8 because the scale would be very small. The views in Figs. 7 and 8 illustrate how by staggering and properly shaping the mechanisms of Figs. 5 and 6 a very compact and efficient arrangement of a plurality of such mechanisms is obtained. In the plane of one bank of connection rods devices are confined for 35 operating three actuators.

35 The actuators 187' (Fig. 7) and 187'' are operated in a manner similar to the operation of actuator 187 previously described. The position of the sixteen totalizers in the machine with respect to actuator 187 is shown. Additional totalizers could cooperate with 187', 187'', 241, or 241' if desired. Actuator 241' is operated in a manner similar to the operation of 241. The actuators are shown converged and offset into a common group for printing and control. If desired they could be left straight and each group

of actuators 187, 241, 187' could then have individual printing and controlling devices.

Printing devices

The data compiled by the machine of the present invention is printed upon a record strip and an issued bill or receipt. The matter printed upon the record media is not all presented on a single line but is arranged on two lines and the groups of related printing are alternated first on 80 the upper then on the lower line across the sheet (see Fig. 16). This style of printing from a single group of type bars is especially effective in printing an address directly beneath a name in the form for mailing.

85 In general, the printing mechanism comprises a type member pivotally mounted on an actuator and cammed to and from printing position by means of eccentrics on a shaft that extends through slots in the actuators and type members. During the rotation of the eccentric shaft the platen for the type are raised and lowered in time to properly receive the impressions of the type carriers which are interspersed and arranged to print two lines of data upon a single operation of 90 the machine. The driving connection to the actuating shaft may be disabled for a no print operation.

95 The actuators converge and are offset to form a single line of slides at the front of the machine. This construction is clearly shown in Figs. 9 and 16 where it is seen that the actuators 187, 241, etc. are adjacent each other and each has a slot 359 by means of which a bar 360 and a comb 361 across the machine, guide the movement of the actuators. In Fig. 9 it may also be noted that pivoted on a pin 362 in each of the actuators is a type carrier 363 provided with an upper set of type 364 and a lower set 365. The type may be numerical, date, or alphabetical, depending on which actuator they are associated with. The sets of type overhang the actuators so as to substantially fill the space between the type (see Fig. 11). There is clearance enough, however, between the overhanging type and the 100 top and bottom of the actuator, to allow the type carrier 363 to be rocked up or down, impressing the type against platens 366, 367, 368, and 369. Certain of the type carriers 363 such as the number, amount, date, and name type carriers, 105 operate with platens 367 and 369, and print above (see Fig. 13) the impressions from the age, agent, policy number and address type carriers which cooperate with platens 366 and 368. Each of the platens is held in a frame 370 (Fig. 12) which is 110 secured to two sliding blocks 371 that slide in slots 372 in the main side frames 50 and 51. A compression spring 373 between the side frames and the platen frames tends to hold the platens into printing position. As the type carriers 363 are 115 rocked up or down, the platens 366, etc. are raised or lowered so that printing will not occur at two points from the same set of type on a typebar. The means for rocking the type carriers and raising or lowering the platens comprises eccentrics 120 374 mounted on a square shaft 375. The means for rotating this shaft 375 will now be described.

125 Referring to Fig. 1A it is seen that disk 73 is provided with a segmental group of teeth 74 which, when the disk is rotated by the main operating mechanism give the gear 376 a complete 130 counterclockwise rotation. This gear 376 is mounted on a stud on side frame 50 and is in mesh with a similar sized gear 377 loosely mounted on a shaft 378 which extends through the side 135 140 145 150

frames. Another gear 379 (Fig. 9) alongside of gear 377 but not in mesh with gear 376, is fastened to shaft 378 and is adapted to turn the shaft when it is coupled to gear 377 by a broad faced 5 pinion 380. Normally this pinion 380 couples the two gears, permitting a printing operation. It may be disengaged at times under control to be described further on in the specification to cause a no print operation.

10 Fastened to the shaft 378, inside each of the main frames is a pair of gears 381 (Fig. 9) in mesh with a pair of gears 382 secured to shaft 375. From the above connections it is apparent 15 that square shaft 375 will normally be given one complete counterclockwise rotation on each operation of the machine.

The eccentrics 374 (Fig. 9) operate in a slot 383 in type carriers 363 and are held in position by means of the shoulder of a slot 384 in the actuators which is purposely made narrower than slot 20 383 so as to confine the eccentrics. Two pairs 25 of eccentrics 374 are devoted to raising and lowering the platens (Fig. 12). One pair of eccentrics cooperates with two plates 385 (one on each side of the machine) for raising and lowering 30 platens 367 and 369, while the other pair cooperates with plates 386 which raise and lower platens 366 and 368. These plates 385 and 386 have slots 387 and 388 for sliding upon studs 389 in the side frames 50 and 51.

Normally the shaft 375 holds the eccentrics 374 so that their eccentricity lies in a horizontal line through the center of the shaft (Fig. 9). One set of eccentrics for the number, amount, operator, date, and name type carriers have their eccentricity to the right side of shaft 375 while the other eccentrics for the age, agent, occupation, policy number, and address type carriers have the eccentricity to the left of shaft 375 as seen in Fig. 9. The pair of eccentrics for plates 385 are also oppositely arranged to those for plates 386. Thus, it is apparent that normally all the type carriers 363 are in a central position. They are held so during the adjustment of the actuators, after which, at the proper time, shaft 375 is rotated.

After 90° of rotation of shaft 375 (Fig. 11) the eccentrics have raised the type carriers including the address type forming the lower line in Fig. 17, and have lowered the type carriers including the name type forming the upper line in that figure. Meanwhile, the eccentrics 374 and plates 385 (Fig. 12) have raised platen 367 and lowered platen 368 out of cooperation with the type. At this point in the printing operation, an impression including the address is taken from the upper type 364 of the raised type carriers which then cooperate with platen 366, while an impression including the name is taken from the lower set of type 365 on the lowered type carriers which then cooperate with platen 369. The reason the platens are raised or lowered out of cooperation with the type is to prevent the name type from printing on line with the address and vice versa.

The shaft 375 is rotated further until at 270° of rotation the type carriers and the platens will assume a position just the reverse of their position at the 90° point. At this point the eccentrics have lowered the type carriers including the address type and have raised the type carriers including the name type. Meanwhile plates 385 and 386 have raised platen 366 and lowered platen 369 out of cooperation with the type, leaving platens 367 and 368 in impression receiving

position. So that at this time an impression including the name is taken from the upper type 364 of the raised type carriers which cooperate with platen 367, while an impression including the address is taken from the lower set of type 365 on the lowered type carriers which then cooperate with platen 368. The completion of the rotation of shaft 375 adjusts all the type carriers to a central position, after which the actuators are returned to normal position.

80 From the above description it is believed clear that during printing, a group of interspersed type carriers, in groups as the amount type (see Fig. 13) or singly as name type will print an upper line of data on two record media, while another group of type carriers interspersed between the above mentioned type carriers and arranged in groups, as the age type, or singly, as address type, will print a lower line of data on the said record media. The record media provided for receiving the printing impressions will now be 90 described.

95 A roll of paper 390 (Fig. 9) is loosely mounted on a shaft 391 between frames 50 and 51. The paper 390 from the roll is fed by means of roller 100 100 and electro 393, between knife blades 394 and 395, and between inking ribbons and the platens 368, 369. After the paper is printed upon by the lower set of type 365 it is severed by movement of knife blade 395 and is allowed to pass out of the 105 machine through a chute having walls 396. The end of knife blade 395 extends through side frame 50 and is connected by a link to a lever 397 (Fig. 1A) which is rocked by a pin 398 in disk 73 upon each operation of the machine. A sample of 110 such an issued bill is shown in Fig. 15. There it is noted that a bill form has been printed by the electro, while the name, address, amount due, etc. has been printed from the type carriers in the machine. On such a bill it is not necessary 115 to print all the information shown on the statistical sheet in Fig. 16, so the lower type are left off certain of the type carriers. It will also be noted in Fig. 15 that part of the address, Oakdale L. I. is lowered on another line below that 120 of the street name, thus forming three lines of print for the name and address. The address may be printed in such a manner by offsetting a portion of the platen 368 and arranging the type 125 on the type carriers accordingly.

125 The supply roll 399 (Fig. 9) of record paper 400 is loosely mounted on a shaft 401 held in frames 50 and 51. This record strip 400 passes between guide rollers 402, 403, between the platens 366, 367, and the inking ribbons, through the guide 130 rollers 404, 405, on to a storage roll 406 which is secured to a shaft 407 adapted to rotate in the side frames 50 and 51. The roll 406 is made accessible for removal by a cover plate 54 which is hinged to the case 53. Examples of printed 135 record strips are shown in Figs. 13 and 14.

135 Fig. 13 shows a record having printed thereon all the data provided in the illustrative machine. The lines of print on this record may be reversed with the name printed on the lower line since the 140 slip is not used for mailing. Such a record may be used for statistical work. Fig. 14 shows a record in the form of a detail strip having one printed item, leaving out certain data, and another printed total with the special sign 334 and 145 the related amount printed on the same line.

140 The pairs of inking ribbons are fed by any ribbon feeding device, many examples of which may be found in the prior art.

145 The devices for feeding the record media are

shown in Fig. 1a. The disk 75 is provided with two sets of gear teeth 76 which cooperate with a gear 408 that is loosely mounted on a shaft 409 which has secured thereto the slip feeding roller 5 392 (see Fig. 9). Operation of the machine and rotation of disk 75 will cause the two sets of teeth thereon to rotate gear 408 two revolutions in a counterclockwise direction. Adjacent gear 408 and of a similar size, is another gear (not shown) 10 which is secured to shaft 409. A broad toothed pinion 410 serves to couple the two gears on shaft 409 when paper feeding is desired. This pinion 410 is pivoted on a link 411 which is connected by a link 412 to the bell crank holding the print 15 disabling pinion 380, previously mentioned, for movement in synchronism. Lever 411 is pivoted on a stud in the side frame 50. From the above connections it is clear that printing and paper feeding will be enabled or disabled simultaneously. 20

When the pinion 410 couples the two gears on shaft 409 together, roller 392 (Fig. 9) upon operation of the machine will feed the paper strip 390. A sprocket (not shown) is also fixed on shaft 409 outside the frame 50. Around this sprocket is wrapped a chain 413 which transmits the movement of shaft 409 to a gear sprocket 414 loosely mounted on a stud 415 in side frame 50. Secured to the sprocket 414 is a gear 416 25 which is in mesh with a gear 417 fastened to the end of shaft 407 (Fig. 9) hereinbefore noted as the shaft carrying the record storage roll 406. From the above description it is obvious that slip 30 390' and record strip 400 will be fed from their 35 supply rolls 390 and 399 simultaneously, and that if slip feeding is disabled the record strip feeding is also disabled.

Control mechanism

40 The machine of this invention is provided with control mechanism for controlling the operation of many functions in the machine according to the comparison of certain data set to control and the data presented in the machine by the 45 punched cards and extents of movement of the actuators under the control of accumulators. By data is meant any name, number, date, address, etc. such as the information printed on the statistical sheet shown in Fig. 13. A certain name, number or date, or a range of such 50 data may be set up by the operator of the machine, and then upon operation of the machine that data will be automatically compared with the name, number, date, etc. tendered to the machine and converted into movement of the actuators to different extents. The range of control 55 may be set by the operator to be above, below, or between the certain names, numbers, or dates set up, or it may be set to control when the data 60 presented by the machine is exactly the same as the data set up.

The terms "range of date", and "above, below or between data" mean the position of names, 65 dates, or numbers in the alphabetic, dating, or numerical scales and may be best illustrated by an example. Taking the name "Smith" for example, the range of data above this name in the alphabetic scale begins with Sn and continues throughout all the names beginning with T, U, V, 70 W, X, Y, and Z; the range of data below "Smith" in the alphabetic scale begins with Aa and continues through B, C, D, etc. up to Sl. The range of data between the names "Brown" and "Smith" includes all the names beginning with the letters 75 Bs—C, D, E, etc. up to the letters Sl.

During the operation of the machine comparison of the data set up with the data presented by the machine takes place and if they are enabled, the control devices then are adapted to change many of the functions of the machine as the machine operates. The printing devices are disabled so that a no print operation occurs. The paper feeding devices are disabled preventing the feeding of the record strip and the issuing of a bill. During totalling operation, the totalizer 80 engaging mechanism may be so controlled as to change the function to a sub-totalling operation and during sub-totalling operations, the totalizer 85 engaging mechanism may be so actuated by the control devices that a totalling operation results. 90

The control of the control mechanism over the totalizers during adding, totalling, or sub-totalling is optional and is in effect only upon the depression of an accumulator control key provided in the machine. 95

In general, the control mechanism comprises settable control knobs which may be positioned to form a name, number, or date. Each knob has slidably attached thereto a finger which is held depressed in contact with the upper edge 100 of a related actuator. This upper edge of the actuator is cut to form three different levels to which the finger may fall as the actuator is moved. The high level maintains a set finger in raised position indicating that the actuator has 105 not moved an extent equal to or above the data set up. The lower lever permits the finger to descend a step indicating that the actuator has moved an extent forming data above the data set up. The lowest level or notch in the top 110 of the actuator, when it coincides with a related finger, allows the finger to descend two steps, indicating that the actuator has been moved to a position in the alphabetic, date or numerical scale, that is exactly the same as the position 115 occupied by the finger.

The above paragraph describes generally the portion of the control devices for sensing and comparing the data set up with the data tendered by the machine by the punched cards or actuator 120 movement. In addition, the control devices comprise a control lever which sets devices to determine the range of control desired. The ranges possible are above, below, between the data set up, or exactly the data set up. 125

After the control lever is set for the range and the control knobs are positioned to form the set up data, the machine is operated. First, the fingers sense and compare the data tendered by the machine with the data set up, then devices 130 under control of the fingers are actuated according to whether the data tendered by the machine is in the control range or not. If the data is in the control range, the control devices are actuated to cause no-printing.

A detailed description of the control devices follows, reference being made to the drawings in the application. 135

Reaching across the machine above the front of the actuators, and secured to the side frames, 140 is a control plate 418 (Figs. 9, 16 and 17) which is provided with notched slots 419 in which control knobs 420 are set to form a name, number, date, etc. The plate 418 has a slot for each of the number, age, amount, agent, operator, occupation, 145 date, policy number, city, and state designating actuators, and two slots located above the first two actuators carrying the name type. Each slot in the plate has a plurality of notches equal in number to the positions of the actuator with which 150

the slot is associated. For example, the date months slot has twelve notches, one for each month.

The knob 420 is flexibly held on a guide plate 421 (Fig. 9) the lower end of which is bent to form a socket 422 in which a finger plate 423 slides vertically. Each of the guide plates 421, as seen in Fig. 16, has a horizontal portion underlying the related slot in plate 418 and an offset portion which terminates in the socket 422 which is poised over a related actuator so that the sliding finger 423 may cooperate therewith. A pair of studs 424 in plate 421 hold it against plate 418 and guide it in movement along the slot 419. The control knob 420 has a shoulder that is of the same diameter as the notches in the slots, and is held down with the shoulder in the notch by a compression spring in the knob that presses between a stud on plate 421 and a ledge inside the knob. This construction inside control knob 420 is not shown as it is an old expedient. The knob is therefore lifted out of any notch, be moved along the slot with plate 421 and dropped into another notch, thus positioning plate 421 and finger 423.

From the above description it is clear that the fingers 423 are guided for vertical movement and each one may be positioned to a number of positions that coincide with the different extents of movement of a related actuator.

The beveled point of the fingers 423 (Fig. 9) normally rests on the shelf of a slotted guide plate 425. Instead of a beveled point on the finger a roller could be mounted on the end of the finger to cooperate with the cam faces on the top of the actuator. When a finger is moved out of normal position, a slot 426 in plate 425 guides its lower end and holds it in contact with the top of a related actuator. The guide 425 reaches across the interior of the machine and is secured to frames 50 and 51.

Each finger 423 is provided with a pin 427 which projects into a long slot 428 in a link 429 that is suspended between a pair of arms 430 loosely pivoted on shafts 431 between the side frames. The slot 428 is long enough to allow finger 423 to assume any of its adjusted positions. The ends of plate 425 guide the link 429. By means of this link and arm construction any downward movement of finger 423 in any of its positions will be transmitted into counterclockwise rotation of arms 430. A spring 432 connected to each rear arm 430 normally holds the parts depressed with finger 423 seeking a lower level.

The top surface of the actuators, upon which the beveled point of finger 423 bears is cut to form three different horizontal levels, a high level 433 (Fig. 10) a lower level 434 and a notch 435. The notch in the actuators is so positioned normally that if the knob 420 is brought to the O position on plate 418, finger 423 will fall into the notch. So also if a finger is moved to the M position and the related actuator moves to an extent required to print M, the finger will fall into the notch. In other words, the notch 435 for each position of the actuator has an exact relative position along a slot 419, and when this relative position is occupied by knob 420 the associated finger 423 will drop into the notch.

The finger 423 may be adjusted to a position above or greater than that represented by the movement of the actuator, in such a case the finger 423 will remain perched upon high level 433. One example of this would be when an amount finger is positioned at 8 and the actuator only

moves to print 6 or 7, the finger would then remain raised. Again, if a date finger should be set at June and the actuator only moved to May, or a name finger stood at P and the actuator only moved to O, the same condition would be obtained.

The finger 423 could also be set in position below or lower than that represented by the movement of the actuator, in such a case the finger 423 would drop one step on level 434, half way between the vertical position assumed when on level 433 or in notch 435. An example of this would be presented when an amount finger is positioned at 8 and the actuator moves to an extent adapting it to print 9, the finger then would be lowered one step. For other examples, if a date finger stood at June and the actuator moved to July, or a name finger stood at P and the actuator moved beyond to Q, similar conditions would be obtained. The springs 432 urging the fingers 423 downward cause them to find the level presented by the actuator.

From the above three paragraphs it is clear that an adjusted finger and its connections will have one of three different vertical positions after the movement of a related actuator. The raised or highest vertical position of the finger shows that it has been adjusted, in its scale, above the character presented for printing by the positioned actuator. A lower vertical position of the finger shows that it has been adjusted below the character presented by the positioned actuator, and the lowest position of the finger shows that it has been adjusted to a character in its scale that is exactly the same as the character presented by the shifted actuator.

Thus, a sort of comparison is made between the data set up with knobs 420 by the operator of the machine, and the data tendered to the machine by movement of the actuators. It is apparent that the front arm 430 will have three angular positions corresponding to the three vertical positions of the finger. The one position will be that shown in Fig. 9, and in the other two positions the arm will be rocked slightly in a counterclockwise direction.

In Fig. 10 is shown another form of control which is adapted to set controls at two points in a scale and in the range of data between the two points exercise control over the data presented to the machine. Two fingers 436 and 437 cooperate with a single actuator. Each of the fingers is mounted in a plate 421 with a knob 420 that can be positioned along a common slot 419. Pivoted in a socket in the side of each of the fingers are the ends of a link 438 which carries a pin 439. This pin protrudes into the slot 428 cut in link 429 and raises this link and its connections in a manner somewhat similar to the action of pin 427 in Fig. 9. The pin 427, however, has only three vertical positions while pin 439 has a few more to be described farther along in this description.

The two knobs 420 associated with fingers 436 and 437 are positioned in two notches along slot 419. For example, if finger 436 is positioned at M in an alphabetic slot, then finger 437 may be positioned at H. If it is desired to increase the range to between G and N a longer link 438 may be used or the link could have a pin and slot connection to the fingers (see Fig. 10a) thereby giving the fingers an adjustable range.

When the actuator is moved, the pin 439 will assume one of a few vertical positions, the location depending upon the positioning of fingers 436 and 437 by upper edges 433, 434, and 435 on the actuators. The positions of pin 439 will be discussed

in the order that the pin descends vertically. It will be assumed that finger 437 stands at 3 and finger 436 at 8; in the date scale they could stand at March and August. In the first or highest position of pin 439 both fingers 436 and 437 are supported on level 433, showing that the actuator has moved less than three steps. In the second position finger 437 contacts level 434 and finger 436 is supported on level 433, as shown in Fig. 14 indicating that the actuator has moved between three and eight steps. In the third position of pin 439, finger 437 is in notch 435 due to the movement of the actuator to 3. In the fourth position both fingers lie on level 434, showing that the actuator has moved more than eight steps. In the fifth position, finger 436 drops into notch 435 indicating that the actuator has moved eight steps.

To avoid repeating the description of the action of certain portions of the control devices when the mechanism shown in Fig. 10 or Fig. 10a is employed, a comparison is made at this point between the devices in Fig. 9 and those in Fig. 10. The first position of pin 439 corresponds to the highest position of pin 427, the second position of pin 439 corresponds to the middle vertical position of pin 427, and the fourth position of pin 439 corresponds to the lowest position of pin 427. With this similarity in mind it is understood that the control, to be described further on, due to the vertical position of pin 427, applies as well to the devices including pin 439. It is contemplated that a "between index control" position be provided, and that the lever in this position will act in the same manner as when in "below index control" position.

Abutting the end of each front arm 430 (Fig. 9) is a plate 441 pivoted on a stud 442 in the end of an arm 443. The plate 441 is held in contact with the end of arm 430 by a spring 444, so that when arm 430 assumes one of its three positions, plate 441 will rock on stud 442 and also assume one of three positions. There is a plate 441 cooperating with each arm 430 and the plates are arranged in groups corresponding to the groups of actuators and control devices, namely, a number group, an age group, an amount group, etc. Each plate 441 has an offset lug 445 which projects over a similar lug on the next lower order plate, the arrangement being such that even if the lower order plate tends to follow the rocking of its arm 430 it cannot do so if the higher order plate is held to the left (Fig. 9) by its arm 430.

The arms 443, upon which the plates pivot, are loosely mounted on a fixed shaft 446 that extends between the main side frames and are urged in a clockwise direction by springs 447. In the normal position, the arms 443 are in a horizontal line and in contact with the top of a stop rod.

The bottom of each plate 441 has a downward extension 448 projecting from a point in the center of two cut-out portions on the plate. The end of the extension 448 is notched and in certain positions of plate 441 the extension is engaged by the cross beam of a lifting bail 449 provided for lifting plates 441. This bail 449 cooperates with all the plates 441 and has a forwardly extending arm on each side of its cross beam, the arms are slotted and held by headed studs to the sides of arms 450 that are fixed to a rock shaft 451 which raises and lowers the bail. Springs between arms 450 and bail arms 449 hold the bail normally forward with the rear stud contacting the end of the slot in bail arm 449.

The means for rocking the shaft 451 and bail

449 is shown in Fig. 1A. A disk cam 72 driven by the main operating mechanism actuates a bell crank 452 which is connected by a link 453 to an arm 454 that is fixed on the end of shaft 451. At the proper time the cam 72 striking a roller 455 on the end of the crank arm rocks the crank counterclockwise about stud 456 in the frame 50 and shifts the link 453 to the right, thereby rocking the shaft 451 and bail 449 in a counterclockwise direction. A spring 457 between a stud in the frame and crank 452 holds the roller 455 against the cam 72 and restores the bail 449 and its connections to normal position.

Cooperating with each group of plates 441 is a stud 458 that lies above the lower forward projection on the plates. The contour of the surface of the plate in cooperation with stud 458, is an arc about stud 442 as a center so that the vertical position of stud 458 is not changed as plate 441 is rocked about its center. However, if any of the plates in the group are lifted by bail 449, stud 458 transmits the motion to a link 459 in which it is mounted. There is provided a link 459 for each group of plates 441, and each link receives the vertical movement of any one of the plates in the group.

The links 459 are guided on their upper ends by slots in a bar between the main frames and guided in the lower portion by having slots 460 through which a rod 461 extends between the side frames.

The extreme lower end of each link 459 carries a pin 462 over which lies the front end of a large control plate 463 (Figs. 9 and 16) that is pivoted on stud 464 in the end of an arm 465. A spring 466 holds each control plate 463 in contact with a pin 462. On raising link 459 the plate 463 is rocked in a clockwise direction so that a shoulder 467 is placed in the path of the cross bar of a control bail 468 that is fixed on shaft 469. Such cooperation of plate 463 and bail 468 will result in the shifting of the plate to the right (Fig. 9) which action is permitted by the rocking of arm 465 on shaft 470. Springs 471, one for each arm, restore the arms 465 and the plates 463 to normal position and normally hold the arms 465 against stop rod 472. The front end of the cross bar on bail 468 cooperates with a surface 463' in the shape of an arc about center 464 to aid in restoring plate 463.

When none of the plates 463 is rocked, the cross bar of bail 468 swings beneath and to the right of the shoulder 467 on the plates. The invariable oscillation of bail 468 upon each operation of the machine is accomplished with the devices shown in Fig. 1A. A cam groove 473 in the gear 69 cooperates with a roller on the end of one arm of a bell crank 474 to rock the crank about its pivot 475 and shift a link 476 connected at one end to the other arm of the crank. The link 476 at its other end is connected to an arm 477 fast on the shaft 469. It is apparent that by the connections described, the oscillatory movement of crank 474 by cam 473 will be imparted to shaft 469, thereby causing oscillation of bail 468.

Movement of any of the plates 463 to the right will push a common rod 477' to the right. This rod is mounted in arms 478' attached to a shaft 479' pivoted in the side frames. Outside the left side frame is another arm 478' to which is pivoted a link 480' which extends to the right in cooperation with certain control elements to be described.

Before discussing the effect of the movement of any of the plates 463 to the right (Fig. 9) it is

deemed advisable at this point to discuss the range control lever and connected devices.

The control lever 440 is pivoted on a stud 473 which projects from the outside of the left side frame 51. At its upper end, the lever is provided with a knob 479 which may be grasped by the operator in moving the lever into one of its five positions. The top of the lever moves along a slot in a plate 480 that is fastened to the case 53. The slot has five notches in which a tab on the lever may be placed to locate and hold the lever in the position to which it is set. The names of these positions and their placement on the plate 480 are shown in Fig. 9.

Pivoted on the lower arm of the control lever 440 at 481 is one end of a link 482, the other end of which is connected to an arm on a cam plate 483 that is pivoted on a stud 484 in the left side frame. By means of this connection the movement of the lever is transmitted to the cam plate. In the position shown (Fig. 9) a hooked end 485 on the cam plate encircles a roller 486 mounted on an arm 487 that is fastened outside the left side frame to a shaft 488. This shaft extends through the machine and has fastened to it, outside the right side frame, a control plate 489 which has cut in its end a cam slot 490 cooperating with a roller 491 on a bell crank 492. This bell crank is pivoted on a stud 493 in the frame 50 and is connected by a spring 494 to another bell crank 495 also pivoted on stud 493 and carrying the broad toothed pinion 380 already mentioned. When the bell crank 492 is rocked clockwise by plate 489, bell crank 495 will be urged by spring 494 to also rock and disengage pinion 380, thus preventing printing.

The movement of bell crank 495 is prevented until the proper time, by an abutment 496 on the bell crank which is obstructed by a stud 497 on a lever 498 connected to the control operating link 476 already discussed. When the proper time is reached for the control function, which is when link 476 is operated, stud 497 will assume the dotted position (in Fig. 9) allowing bell crank 495 to rock clockwise and perform the various control functions to be described. Pivoted on the end of the vertical arm on bell crank 495 is a link 499 which forms an operating connection to the controlled devices.

A stud 500 on the side of the link 480', previously described, contacts the side of arm 487 so that when bail 478' is rocked this movement may be transmitted to plate 489. A slot 501 in link 480' surrounds stud 486 and guides the link without interfering with movement of arm 487.

From the above broad outline of the control devices it is apparent that control plate 489 is rocked by single or combined action upon it by two trains of connections; the one train consisting of fingers 423, plates 441, bail 449, plates 463, etc.; the other train comprising control lever 440 and cam plate 483. The various effects of the positioning of the control lever is described in the next portion of this specification, then the effects of the raising and lowering of fingers 423 is taken up, and then the combined effect of the control devices is discussed. The object of the control devices is to rock the bell crank 495 in a clockwise direction at the proper time to change the printing function of the machine.

When the lever 440 is in the "print" position, the hook 485 on plate 483 engages the roller 486 and holds the plate 489 with the upper end of the cam slot engaging the roller 491 and holds bell crank 492 in normal position. In this position of

bell crank 492 a tab 502 on it holds the other bell crank 495 so that the pinion 380 remains in mesh with gears 377 and 379. A printing operation is effected and the controls do not alter the normal functioning of the machine when the lever 440 is in "print" position. 80

In the next "below index" position of the lever 440, the plate 483 is rocked so that the pin 486 has a relative position to the plate as shown by dotted pin 486' (Fig. 9). Arm 487 is not rocked by this movement of lever 440, but the pin 486 is now clear of hook 485 so that arm 487 may be rocked if bail 478' is actuated. The plate 489 and arm 487 are held rocked clockwise with the roller 486 against the cam faces on plate 483 by a spring 490 between plate 489 and the main side frame. It may be noted that any rocking of arm 487 and connected control plate 489 in a counterclockwise direction will shift the roller 491 and bell crank 492 by means of the cam faces in the cam slot 490. If plate 489 is rocked up one step the cam face 503 in slot 490 will rock bell crank 492 in a clockwise direction. Two steps of upward rocking movement of plate 489 will bring the cam face 504 in cooperation with roller 491 and position bell crank 492 in normal position (Fig. 9). Another step of movement of plate 489 brings the lower end of cam slot 490 into cooperation with roller 491 and again rocks bell crank 492 clockwise into controlling position. 95

Turning again to the positioning of lever 440 it is noted that when the same is put into the "exact index" position a cam face 505 on plate 483 rocks arm 487, and pin 486 assumes the relative position 486'' to the cam plate. In this position of arm 487 the cam face 503 is placed in cooperation with roller 491, and bell crank 492 is rocked clockwise with spring 494 urging bell crank 495 to assume its controlling and no print position. At this time, if plate 489 is not rocked another step upward by bail 478', a no print and controlling operation will occur. 115

In the next "above index" position of lever 440, the pin 486 has a relative position 486''' to the plate 483. In this position of cam plate 483, the arm 487 and control plate 489 are rocked one step with roller 491 engaged by cam face 503 as was the case in "exact index" position. In the "above index" position, however, a spacing finger 506 on a slide 507 is placed between stud 500 and arm 487 so that any movement of bail 478' will be transmitted immediately to arm 487, whereas in the "exact index" position the pin 500 has to travel idly for one step of movement before contacting with the side of arm 487. From the above it is clear that bail 478' has to rock two steps under "exact index" control to produce the effect that is produced by one step of movement of the same in "above index" control. The slide 507 carrying the spacing finger 506 is held on cam plate 483 by pin and slot connections. 125

The "no print" position of lever 440 is the extreme rear position of the lever. When the lever is put in this position, cam plate 483 is rocked so that a cam 508 engages the roller 436 and rocks arm 487 until the stud 486 is encircled by a hook 509 on the lower end of the cam plate. When arm 487 is in this position the plate 489 is placed with the lower end of slot 490 engaging roller 491 thus rocking bell crank 492 and holding it in a position urging bell crank 495 into no-printing and controlling position. 135

Turning back now to the connections of the bail 478' that cause it to rock either one or two 150

steps in a counterclockwise direction about shaft 479', it is noted that in order that bail 478' may be rocked, projection 448 of one of the plates 441 must be above the bail 449 so that link 459 may 5 depress plate 463 into engagement with bail 468. The various conditions under which projection 448 is positioned to allow bail 449 to engage it will now be discussed. An example will be taken of every case that may occur when knobs 420 are 10 set to form a number, name, or date and the actuators moved to position the type bars to print a number, name, or date. It is noted the actuators may be moved under control of a punched card or under control of a totalizer wheel. So 15 that control of the various functions of the machine may be had even without use of the punched card controlled devices.

Turning now to the discussion of the various conditions that exist in the machine when comparing the data set up by the operator with the data presented by movement of the actuators. Taking a number 78,365, for example, as the controlling factor, this number may be set up on the control plate by arranging the numerical 20 knobs 420 along their slots until they are positioned to form the number 78,365. In the normal position of the actuators all the numerical fingers 423 are held up on the upper lever 433 on the numerical actuators and the projections 448 25 on plates 441 will appear to the left of the cross bar of bail 449. Upon movement of the actuators, if the highest order actuator, the tens of thousands one, moves less than seven steps, the related finger 423 will remain on lever 433 and plate 441 30 will be held to the left with its offset tab 445 holding all the lower plates to the left, regardless of the extent of movement of the actuators related to the lower order plates. For instance, the number moved to by the actuators may be 35 40 69,999, whereupon all plates 441 except the higher order plate are urged by springs 444 to swing to the right but they cannot do so because they are held by the higher order plate.

Thus, it is clear that if the number presented 45 by movement of the actuators is less than the number set up by the control knobs, the plates 441 are not lifted by bail 449 and bail 478' is not rocked to the right by its associated parts. The same condition would exist if the letters MEN 50 were set up to control and the name actuators moved to LYX; or if the date June 15, 1920 were set up to control and the date actuators moved to May 31, 1921.

Another condition would present itself, if, upon 55 movement of the actuators, the highest order actuator would move beyond 7, to 8 or 9. The related highest order figure would then rest down on level 434 and projection 448 would be directly above the cross bar of bail 449 ready to be operated. The highest order plate 441 and its projection 448 will maintain this operative position regardless of the movement or lack of movement of the lower order actuators and plates 441. If the lower order actuators are moved an extent 60 coinciding with the set up, say the number presented by the actuators is 98,365, the related fingers will fall into notches 435 and plates 441 will tend to swing to the extreme right, but they will be obstructed by the tab 445 of the highest order 65 plate which is held in operative position. On the rocking of bail 449 the plate 441 is lifted and through the connections already discussed, bail 478' is swung slightly to the right. From the 70 above, it may be noted that when the number presented by the movement of the actuators is 75

greater than the number set up by the control knobs, at least one plate 441 will be lifted by bail 449, and bail 478' will be rocked. Conditions similar to these would prevail if the letters MEN were set up to control and the name actuators moved to NEN; or if the date June 15, 1920 were set up to control and the date actuators moved to July 15, 1921.

Another condition would prevail if the actuators moved exactly the amount set up, namely 80 78,365. Then, all the fingers 423 would fall into notches 435 and all plates 441 would swing together to the right, placing projections 448 to the right of the cross bar on bail 449 and out of its path. The bail 478' would not be moved under such conditions.

A still different condition would exist if one or a few of the higher order actuators moved to the same digit or digits that were set up by the control knobs, say a number such as 78,432 were 85 presented by the actuators. The two higher order fingers 423 would fall into notches 435 and related plates 441 would swing to the extreme right. The hundreds order plate 441 and finger 423 would then become, in effect, the highest order, and if 100 the hundreds actuator moved to 4 the related plate 441 would be positioned above bail 449 for actuation. However, if a number less than 3 is presented by the hundreds actuator the related hundreds plate remains to the left and holds all 105 the lower order plates in inoperative position. Thus, it is clear that not only by comparing the magnitude of the highest order of the data set up is control exerted but in these devices every 110 denomination of a number, or letter of a name is capable of determining whether the control devices should function or not, depending upon the magnitudes of the data presented and the data set up. Analogous cases would be presented if the aforementioned name or date were set up 115 and MEX or Aug. 15, 1923 were presented by the related actuators.

When the control lever 440 is moved into "exact index" position devices are put into effect that change the relations between the devices for moving bail 478'. This is done to secure a control for an exact comparison of data set up with data presented. The bail 478' is adapted to be rocked a greater extent under this type of control.

An arm 510 on lever 440 is provided with a 125 roller 511 which, when the lever is in "exact index" position, cams an arm 512 (not shown) fastened to a shaft 513 outside the left side frame. Inside the main frames the shaft 513 has mounted thereon a pair of arms 512 for 130 each group of related fingers 423 and set up devices. A spring normally urges this assemblage counterclockwise slightly to the left when not cammed to the right by roller 511. Slidably mounted on each pair of arms 512 is a 135 coupling bail 514. Each of these bails has two depending slotted arms that guide them for vertical movement on studs in the arms 512. Pivoted to each of the links 429 and depending therefrom is a bar 515 which is guided in its 140 vertical movement by a slotted plate surrounding its lower end. The bars 515 each have a horizontal notch 516 into which the cross bar of a coupling bail 514 can fit. Normally the bails 514 stand clear of the notches 516 and 145 do not interfere with vertical movement of bars 515. However, when lever 440 is put in "exact index" position the bails 514 are inserted into notches 516 so that each bail will couple together the bars 515 of a related group of con- 150

trol devices, thereby causing all the fingers 423 of a group to move as a unit and to stand on level 433, or level 434, or to fall into notch 435 in the actuator as a unit. The fingers 423 5 do not necessarily have to remain in the same line as shown in Fig. 9 but they can be set to any number, name, or date and still they will be coupled as a unit and only move down 10 into notches 435 as a unit when the actuators are moved to extents that form data corresponding to that set up by the control knobs.

The extreme left hand arm 512 inside the left side frame has an extension to which is connected the right hand end of a horizontal arm 15 of an L-shaped member 517. The mid-section of member 517 surrounds the shaft 461 previously mentioned so that when the arms 512 are cammed to the right, shaft 461 is slid along horizontal slots in the side frames, thus swing- 20 ing all the links 459 to the right until the pins 462 in the lower ends assume the dotted line position shown in Fig. 9. With the links 459 so positioned if any one of them is lifted it will tilt the plate 463 twice as great an extent than 25 it is tilted when links 459 are in the normal position shown in Fig. 9. When so tilted, plate 463 presents a shoulder 518 to the bail 468. This shoulder 518 is a step closer to the cross bar of bail 468 than the shoulder 467 so that when plate 30 463 is moved to the right during "exact index" control, bail 478' is rocked twice the amount that it is rocked under the "above" or "below" index control.

The member 517 has a vertical arm that co- 35 operates with bail 449. When the member 517 is moved to the right by the camming of plate 512, the upper end of this vertical arm strikes the bail 449 and carries it to the right so that the cross bar of the bail is two steps to the 40 right of the projections 448. In order for the projections 448 to be placed in a position so that plates 441 will be lifted by bail 449, the fingers 423 will have to fall into notches 435 allowing plates 441 and the projections 448 to 45 swing into the extreme right hand position.

From the above description it is clear that during "exact index" control the fingers 423 of a related group are coupled together, and the bail 449 is shifted so that only when the fingers 423 drop into the exact notch 435 will the plates 441 be lifted, and if any plates 441 are lifted they will condition plates 463 so that bail 478' will receive twice its usual amount of movement.

55 A device for governing the amount of swinging movement of plates 463 is shown. This device is not necessary to the correct functioning of the control mechanism as it may be dispensed with and still the control devices are 60 fully operative. A link 520 is connected to the bottom end of lever 440 and to the top end of an arm (not shown) on shaft 521 outside the left side frame. A pair of arms 522 are fastened to the shaft 521 inside the side frames 65 and support a cross rod 523 that underlies all the plates 463. The lower edges of plates 463 are notched to limit the plates rocking movement by abutting the rod 523. In the "print" position of lever 440 the rod 523 cooperates with 70 shoulders 524 on plates 463 holding them all up out of cooperation with bail 468. In the "below index" and "above index" positions of lever 440 the rod 523 underlies notches 525 and 526 respectively in the plates, and limits their down- 75 ward movement to one step so that shoulder

467 is in operative relation with bail 468. In the "exact index" position of lever 440, the rod 523 is placed beneath a deep notch 527 on the plates 463 so that the plates may swing until shoulder 518 is presented to the bail 468. The 80 notches 525, 526, and 527 are long enough to allow the plates 463 free sliding movement to the right as they are actuated by the bail 468.

When bail 478' is actuated it does not necessarily mean that control is to be effected, for 85 roller 491 may be moved into either cam portion 503 and 504, it is only through the combined effect of the range control set by lever 440, and the comparison made by fingers 423 between the data presented by the actuators 90 and the data set up, that control is effected.

At this point in the specification the combined effect of the two trains of controlling mechanism, namely, the devices under control of fingers 423 and devices under control of lever 440, may be 95 considered, and the positioning of the bell crank 495 under such dual control will be discussed.

Considering first the conditions prevailing when lever 440 is in the "print" position, it is noted that the rod 523 on the lever 522 holds all 100 the plates 463 out of cooperative relation with bail 468, thus preventing movement of arm 487 by the bail 478' and its connections. It is contemplated that an interlock may be provided between lever 440 and knobs 420 so that when the lever 105 is in "print" or "no print" position the knobs are held in the position shown in Fig. 10. It is also noted that in this position of lever 440 the hook 485 on cam plate 483 holds the roller 486 so that both bell cranks 492 and 495 are held 110 in normal position and no control is exercised to change any of the functions of the machine.

When the lever 440 is in "below index" position and the control knobs are positioned to form a controlling set up, the following conditions are 115 obtained. The roller 486 and bell cranks 492 and 495 remain in their normal position when the lever 440 is moved to "below index" position. However, lever 522 is swung so that the rod 523 is placed below a cut out portion 525 on plates 463, 120 thus allowing them to drop one step if the movement of the actuators presents data greater in magnitude than the data set up by knobs 420. If the actuators are so moved and any one of plates 463 are lowered, the bail 478' is swung 125 slightly to the right and by means of the cooperation between pin 500 and arm 487, controlling plate 489 is rocked so that roller 491 is cammed into portion 503 of cam slot 490, thus putting bell crank 492 into a position wherein spring 494 urges 130 bell crank 495 into controlling position where it is allowed to rock at the proper time when stud 497 is withdrawn from beneath shoulder 496 on bell crank 495.

From the above explanation it is clear that 135 whenever the lever 440 is in "below index" position, and the data presented by the actuators is of a greater magnitude than the data set up, the control devices are actuated to change many of the functions of the machine. The machine 140 functions in the normal way only if the data presented is below, in its scale, the data set up. Because the devices when so positioned provide such a comparison, this kind, or range, of control is named "below index". If the operator of the 145 machine wishes it to perform in the normal fashion, i. e., printing, sorting, accumulating, etc., only when the data submitted is "below" that arbitrary name, number, and/or date which he has set up, he chooses this range of control. 150

- In the "exact index" position of lever 440, the roller 486 is cammed to the right and the roller 491 stands in cam portion 503 with the bell crank 492 urging bell crank 495 into controlling position. The rod 523 on lever 522 is positioned so that it is below the notch 527 on plates 463 so that the plates may descend two steps if the movement of the actuators presents data exactly the same as that data which is set up by the control knobs.
- 10 If the actuators are so moved and a plate 463 is lowered, the bail 468 swings the plate and bail 478' two steps to the right. When bail 478' is so moved the pin 500 in link 480' moves towards arm 487, one step of such movement is idle and 15 is used to place the pin in contact with the arm, the next step of movement rocks the arm 487 and connected plate 489 so that the roller is forced into cam notch 504 in cam slot 490 and the bell crank 492 resumes its normal position. From the 20 above description it is apparent that whenever the control lever is in "exact index" position, and the data presented by the actuators is different from the data set up, the control devices are actuated to change many of the functions of the machine.
- 25 The machine functions in its usual way only if the date presented is exactly the same as the data set up. Therefore, this type of control is named "exact index" control. Thus, it is clear 30 that the operator of the machine may set the control devices so that the machine prints, accumulates, takes a total, etc., only when a certain name, number and/or date is among the data presented to the machine by the movement of 35 the actuators under control of a punched card or the totalizer wheels.
- If lever 440 is put in "above index" position, the cam plate 483 rocks control plate 489 so that the roller 491 stands in notch 503 of the cam slot 40 490, thus urging bell crank 495 into controlling position. At the same time projection 506 is inserted between pin 500 and arm 487 so that all the movement of the bail 478' is transmitted to the control plate 489. The rod 523 on lever 45 522 is moved to a position beneath shoulder 526 on the plates 463 so that they may drop one step if the movement of the actuators presents data greater in magnitude than the data set up on the control plate 418. If the actuators are so moved 50 and any of plates 463 are lowered, the bail 478' is later swung slightly to the right by bail 468; and by means of pin 500, projection 506, and arm 487, controlling plate 489 is rocked so that the roller 491 is cammed into portion 504 of cam slot 490, 55 thus positioning the bell crank 492 back into its normal position wherein it does not urge the bell crank 495 into controlling position. From the foregoing it is clear that whenever the lever 440 is in "above index" position and the data 60 presented by the actuators is below, in the alphabetic, date, or numerical scales, the data set up, the control devices are actuated to change many of the functions of the machine. The machine functions in the normal manner only if the data presented is above, in its scale, the data set up.

Therefore, this kind of control is called "above index" control. When the operator of the machine chooses such control he will expect the machine to print, add, take totals, feed paper, etc., only when the data on the punched card or totalizer wheel is "above" that certain name, number, or date which he has set up by the control knobs.

The condition of the control devices as positioned by the lever 440 in "above index" posi-

tion would serve equally as well on "between index" control, in connection with the devices shown in Figs. 10 and 10a as already described. The bell crank 495 would be urged into controlling position unless the data presented by the actuators was between the limits of the data set up by the pairs of knobs 420. Under the latter condition the bell crank 492 is pushed back into normal position also holding the bell crank 495 in that position. It is to be noted that during "between index" control if the data presented to the machine is not between the range of values in the alphabetic date, or numerical scale, set up by knobs 420, the control devices are actuated to change some of the functions of the machine in a manner similar to that described in connection with the other ranges of control.

In the extreme right hand position of lever 440, the "no print" position, roller 491 is held in the bottom of cam slot 490 so that spring 494 urges bell crank 495 into controlling position. As long as lever 440 is held in this position, a controlling position is assumed by bell crank 495 on each operation of the machine. The paper feeding and printing devices are then disabled or controlled while the control over the accumulating and totaling functions is optional and under control of the key 530 (Fig. 1B).

The connections from the controlling devices to the various other mechanisms in the machine to enable the said devices to change the functioning of the said mechanisms will now be considered. It has already been noted that when the bell crank 492 is rocked slightly in a clockwise direction, the lug 502 is moved away from bell crank 495 and spring 494 urges this controlling bell crank into its controlling position. At the proper time for the control devices to function the link 476 is shifted and stud 497 is moved from beneath shoulder 496 on the controlling bell crank and it swings in a clockwise direction into its controlling position.

It has already been described how the printing function is disabled in the machine when the broad toothed pinion 380, mounted directly on the bell crank 495, is disconnected from gears 377 and 379. The connections from the controlling bell crank 495 for preventing paper feeding, consisting of link 412, (Fig. 1A) arm 411, and broad toothed pinion 410, have also already been discussed. The connections for controlling other functions in the machine will now be described.

To the end of the vertical arm of the controlling bell crank 495 (Fig. 1A) is pivotally held one end of a link 499 that extends down and to the right (Fig. 1B) where its other end is attached to the arm 531 on the sorting shaft 115. When the bell crank 495 is moved into its controlling position the connections above mentioned will swing the sorting blade 116 into the dotted position, thereby diverting the card 79, associated with the item causing the control devices to function, into the bin 111.

At about the center of link 499 (Fig. 1B) there is loosely connected one end of a lever 532 pivotally mounted on a fixed stud 533 in frame 50, and having pivotally connected to its other end a link 534. This link serves to engage and disengage the totalizers under control of the control devices, thus changing the function of the totalizers from adding to non-adding, from totalling to sub-totalling, and vice versa. Cut opposite each other in the end of the link 534 are two notches 535 and 536 each of which is adapted to cooperate with pins 537 and 538 respectively, that are

- placed on the opposite sides of the pivot of a lever 539. This lever 539 is pivotally mounted on a stud 540 in side frame 50 and has a pin 541 on the upper arm in engagement with a slot that 5 is cut in the slide 339 described hereinbefore. When the slide 339 is shifted to the right to disengage the totalizers from the actuators the pin 538 is placed to the left of a vertical line through pivot 540 and pin 537 is positioned to the right, 10 as shown in Fig. 1B. In this position of the pins, the right edge of upper notch 535 is in line with the right side of pin 537 and the left edge of the notch 536 is in line with the left side of pin 538. When the slide 339 is shifted to the left to engage 15 the totalizers with the actuators, the lever will oscillate and pin 538 will appear to the right of pivot 540 and pin 537 to the left. Then the pins 537 and 538 are in line with the ends of notches 535 and 536 opposite to the ends with which they were 20 aligned in the disengaging position of slide 339.
- Normally the link 534 is held out of cooperative relationship with the pins 537 and 538 by a bell crank 542. This crank 542 is pivoted on a stud 543 in frame 50 and has a converging notch 544 in its lower arm which confines a pin 545 on the link. The end of the upper arm of the bell crank is loosely attached to the end of the accumulation control key 530 so that if this key is depressed and latched by notch 546 to the case 53, 25 the bell crank 542 is rocked clockwise into a position whereon the pin 545 is released from the confines of notch 544 and the link 534 may be lowered or raised into cooperation with lever 539.
- During adding operation if the key 530 is depressed the spring 547 lifts link 534 so that pin 35 537 enters into notch 535. Then, upon operation of the machine, the totalizers are put into engagement with the actuators by the shifting of slide 339 to the left by the ordinary engaging devices 40 and pin 537 is placed in contact with the left edge of notch 535. Upon operation of the control devices if bell crank 495 (Fig. 9) assumes the controlling position, link 534 is moved to the right, pushing pin 537 and slide 339 before it, 45 thus disengaging the totalizers and causing a no-add operation. The control devices are timed so that the totalizers are disengaged before the actuators start the adding movement of the actuator reciprocation.
- 50 The same controlling operations are employed if the machine is performing a sub-totalling operation with key 354 depressed, only at this time the result would be that the operation is changed to a totalling operation. During a sub-totalling operation the totalizer is engaged with the actuators early in the operation of the machine and the wheels of the totalizer are turned back to their zero positions before the control devices are 55 permitted to be actuated. So that after half of the sub-totalling operation is over, if the control devices do not push slide 339 to the right and disengage the totalizer it will remain in mesh with the actuators and turn the totalizer wheels back to the number that was previously cleared out.
- 60 However, if the control devices do act to disengage the totalizer, the totalizer wheels remain at zero. Thus, the control devices serve to change a sub-totalling function into a clearing total function.
- 65 When the total key 356 is depressed the relation between the control devices and the totalizer engaging devices is changed, i. e., providing the key 530 is also depressed to permit control. A spring 548 is attached to the end of the total key 70 356 and is attached in turn at its other end to a
- spring clip 549 which has a slotted end that confines a pin in the end of link 534. The slot in the spring clip 549 normally allows the link to rise under the tension of spring 547, but when the total key is depressed the top end of the slot in the clip engages the pin on link 534 and by means of the heavy spring 548 the link 534 is lowered until the notch 536 in it engages the pin 538. During the first part of the totalling operation of the machine the slide 339 is shifted to the left by the engaging mechanism, thus engaging the selected totalizer with the actuators. Then, as the actuators move, the totalizer wheels are turned back to zero, so far the operation being just as it is in sub-totalling. However, at this point the engaging devices shift slide 339 to the right to disengage the totalizer wheels to leave them standing at zero as they should be after a clearing operation. When the slide 339 is so shifted the pin 538 comes into contact with the left side of notch 536 and if link 534 is shifted by the control devices then slide 339 is again shifted to the left, again engaging the totalizer with the actuators which turn the wheels back to the number that was cleared out during the 100 first part of the operation of the machine. From the above, it is clear that if the control devices are actuated during a totalling operation of the machine, the operation is changed to a sub-totalling operation.
- 105 While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.
- 110 1. In a printing mechanism, a plurality of sets of type holders in a single group, alternate type holders belonging to the same set, means for adjusting the type holders, a plurality of platens, and means for alternately impressing the type 115 holders against the platens so as to form a plurality of lines of print on a record.
- 120 2. In a printing mechanism, a plurality of sets of type holders in a single group, alternately arranged type holders belonging to the same set, means for adjusting the type holders, a plurality of platens, and means for alternately impressing the sets of type holders against the platens so as to form a plurality of lines of print on a record, each line relating to a different character- 125 130
- 135 3. In a printing mechanism, a set of name printing type bars and a set of address printing type bars alternately placed in a parallel group, means for differentially setting the type bars, a platen for each set of type bars, a record medium, and means for alternately impressing the type bars against the platens so that a name and address is printed in two lines on the record medium in the regular mailing form.
- 140 4. In a printing mechanism, two sets of type bars arranged in a parallel group, alternate type bars belonging to the same set, an operating shaft, a pair of platens one for each set of type bars, eccentrics on said shaft with alternating changes of eccentricity along the shaft, each eccentric cooperating with a type bar, the arrangement being such that upon turning said shaft the sets of type bars will be alternately impressed 145 against their platens.
- 150

5. In a machine of the class described, record material, a plurality of type bars, a plurality of platens for impressing a plurality of lines of print from the type bars on said record material, a shaft having an eccentric for each platen placed at different positions on the shaft circumference, and means for rotating the shaft so that said platens will be brought alternately into printing position. 80
- 10 6. In a printing mechanism, record materials, a plurality of sets of type bars having a plurality of sets of type, a plurality of platens for said type, and an operating shaft provided with eccentrics which cooperate with the platens and the type bars to operate them alternately so as to impress a plurality of lines of print on the record materials. 85
- 20 7. In a printing mechanism, record media, a plurality of sets of type bars with upper and lower type, a plurality of platens for the upper type and a plurality of platens for the lower type, an operating shaft, and eccentrics on said shaft which cooperate with said platens and said type bars, the eccentrics of a related set of type bars each having a common radial position on the circumference of said shaft, to alternately raise and lower the platens and type bars so as to impress a plurality of lines of print on each record medium. 90
- 25 30 8. In a machine of the class described, two sets of type bars having type on their upper and lower sides, record media for the upper and lower type, a pair of platens for the upper type and a pair for the lower type, one of each pair of platens being for one set of type bars and the other platen being for the other set, a shaft carrying eccentrics for raising and lowering the type bars and platens, the arrangement being such that upon a partial rotation of said shaft one set of type bars will be lowered while the other set is raised meanwhile the upper platen not associated with the type raised will be lifted out of printing position while the lower platen not associated with the type lowered will be depressed out of printing position, the other two platens staying in printing position; further rotation of the shaft will reverse the positions of said type bars and platens so that a complete rotation of said shaft will cause the printing of two lines of print from the two sets of type on each record medium. 100
- 35 40 45 50 9. In a machine of the class described, record material, a plurality of sets of type bars in one group in which the related type bars of a set are alternately placed between the type bars of another set, a plurality of platens, an operating shaft having an eccentric cooperating with each type bar, the eccentrics for each related set of type bars being placed at different radial positions on said shaft, and means for rotating said shaft to impress the different sets of type bars alternately against the platens so as to form a plurality of lines of print on the record material. 105
- 55 60 65 70 10. In a machine of the class described, record material, a plurality of slotted type bars, means for adjusting said type bars differentially, an operating shaft, a platen, and cams on said shaft operating in said slots to impress the type bars against the platen and print on said record material. 110
- 75 11. In a machine of the class described, record material, two sets of type bars, means for positioning the type bars differentially, a pair of platens one for each set of type bars, a shaft carrying eccentrics for raising and lowering the type bars and platens, means for operating said shaft so that one set of type bars is lowered and the other set raised and the platen not associated with the type bars raised is depressed out of printing position while the other platen remains in printing position, said means also operating said shaft to reverse the positions of the type bars and platens, and type elements on said bars for printing two lines of print, one directly beneath the other on the record material. 115
12. In a machine of the class described, a plurality of type bars, means for determining the extent of movement of said type bars, means for moving said type bars, printing devices for recording the data presented by the type bars, and control devices under control of said type bars for controlling the actuation of said printing devices according to whether the data presented is above or below, in its scale, a requirement set by said control devices. 95
13. In a machine of the class described, a plurality of type bars, means for determining the extent of movement of said type bars, means for moving said type bars, printing devices for recording the data presented by the type bars, and control devices under control of said type bars for controlling the actuation of said printing devices, the actuation depending whether the data presented is between certain limits, in its scale, set by said control devices. 100
14. In a machine of the class described, a plurality of type bars, means for determining the extent of movement of the type bars, record paper, devices for recording on said paper the data presented by the type bars, paper feeding mechanism, and control devices under control of cam formations on said bars which determine whether the paper will be fed or not depending upon the extent of movement of the type bars. 110
15. In a machine of the class described, a plurality of type bars, means for determining the extent of movement of the type bars, record paper, devices for recording the data presented by the type bars on said paper, paper feeding mechanism, and control devices under control of said type bars which determine whether the paper will be fed or not depending whether the data presented is above or below in its scale, a requirement set in said control devices. 115
16. In a machine of the class described, a plurality of actuators, means for controlling the extent of movement of said actuators, record paper, devices for recording the data presented by the actuators on said paper, paper feeding mechanism, manipulative control elements, two for each actuator and settable variably to form a pair of names, numbers or dates, and control devices which determine whether the paper will be fed or not depending whether the data presented is between certain limits in its scale, said limits being set by said manipulative control elements. 120
17. In a machine of the class described, type bars, means for printing from said type bars, devices for enabling or disabling said printing means, and means controlled by said type bars for changing said devices from enabling to disabling control or vice versa during operation of the machine. 130
18. In a machine of the class described, a plurality of actuators, means for differentially moving said actuators, mechanism cooperating with said actuators for printing the data presented by the actuators, manipulative control elements, two 135
- 140
- 145

for each actuator and settable variable to form a pair of names, numbers, and/or dates, and control devices for comparing the data in the range of the set elements with the data presented by 5 the actuators and adapted to disable said mechanism according to the result of the comparison.

19. In a machine of the class described, record cards having index points arranged in combination to represent record data, type members posi-

tioned under control of said cards, a plurality of platens, record material, and a cam shaft in co-operation with said members and said platens and adapted to bring adjacent type members against the platens at timed intervals so as to impress a plurality of lines of record data on said record material.

JOHN W. ARMBRUSTER.
